TELEPHONE SYSTEM

Clarence E. Lomax, Oak Park, Ill., assignor to
 Associated Electric Laboratories, Inc., Chicago,
 Ill., a corporation of Delaware

Application October 13, 1938, Serial No. 234,751

31 Claims. (Cl. 179—17)

The present invention relates to automatic telephone systems and more particularly to improved line circuits associated with the lines thereof and to improved combined line and cut-off relays adapted for use in the line circuits thereof.

In an automatic telephone system, usually a line circuit is individually associated with each line thereof, which line circuit conventionally 10 comprises separate and distinct line, cut-off and lockout relays mounted upon a supporting panel. These three relays are ordinarily so connected and arranged that the automatic switches in the system having access to a line are controlled in accordance with the various operations thereof to set up, by way of the line, outgoing call connections from and incoming call connections to a subscriber substation associated with the line, and that the line is marked as busy to the automatic switches having access thereto in the event 20 a fault appears upon the line. Further these relays are so connected and arranged that the automatic switches in the system having access to the line are controlled in accordance with other operations thereof to set up, by way of the line, reverting call connections between two of the subscriber substations associated with the line, in the event the line is of the multiparty type.

While line circuits of the type briefly described 30 above are entirely satisfactory in operation, they are more expensive to manufacture and to maintain in service than is desirable, primarily due to the fact that three separate and distinct relays are required in each line circuit in order to render the previously-mentioned services by way of the associated line.

Accordingly it is an object of the present invention to provide an improved line circuit adapted for use in an automatic telephone system 40 which comprises line and cut-off relays, which two relays are so connected and arranged that the automatic switches in the system are controlled thereby to render, by way of a subscriber line with which the line circuit is associated, calling, called and reverting call services to the subscriber substations associated with the subscriber line.

It is another object of the invention to provide an improved line circuit of the type described 50 adapted for use in an automatic telephone system which is economical to manufacture and which is positive in operation in order to control the automatic switches in the system in a thoroughly reliable manner, whereby the desired services may be rendered to the subscriber sub-

stations associated with the subscriber lines in the system.

Another object of the invention is to provide in a telephone line circuit an improved combined line and cut-off relay which is of simple and rugged construction and arrangement, and which is economical to manufacture and thoroughly reliable in operation.

It is a further object of the invention to provide in a telephone line circuit a combined line 10 and cut-off relay including a support, line and cut-off magnets carried by the support, the line magnet being of the two-step operating type, and an improved mechanical arrangement for controlling the operation of the line magnet.

A further object of the invention is to provide an improved automatic telephone system in which there are incorporated line circuits of the type described, each including a combined line and cut-off relay of the construction noted.

The features of the present invention are illustrated as being incorporated in an automatic telephone system including a plurality of subscriber lines, some of the lines being of the multiparty type, each line having a line circuit of the type described incorporating a combined line and cut-off relay of the construction noted individually associated therewith, and a number of finder-connector links for setting up connections between the various lines. A number of subscriber 30 substations are associated with each of the lines of the multiparty type; and a distributor of the preselective type is provided for the purpose of assigning the links to the use of calling ones of the lines in a predetermined order. Two different forms of the line circuit are illustrated which may be associated alternatively with each of the lines in the system. In the first form of the line circuit the line and cut-off relays are so connected and arranged that a calling line is marked 40 as busy to the connector switches of the links having access thereto when the associated line is found by the finder switch of an idle one of the links having access thereto. In the second form of the line circuit the line and cut-off relays are so connected and arranged that a calling line 45 is marked as busy to the connector switches of the links having access thereto immediately the call is initiated on the line and prior to the time the line is found by the finder switch of an idle one of the links having access thereto. The combined line and cut-off relay incorporated in each form of the line circuit comprises a support, line and cut-off magnets carried by the support, a movable contact actuating member

50

55

operatively associated with the line magnet, a movable contact actuating member operatively associated with the cut-off magnet, contacts respectively associated with the members, and 5 latching means for controlling the operation of the first-mentioned member in two steps.

In accordance with one feature of the invention the line circuit is adapted for use in an automatic telephone system including a line accessible to an automatic switch, and comprises, in combination, line and cut-off relays, the line relay having first and second operated positions, means responsive to the creation of a calling condition on the line for causing the line relay to be operated to the first position, means responsive to the seizure of the line by the automatic switch for causing the cut-off relay to be operated, means controlled by the operation of the cut-off relay for causing the line relay to be operated to the second position, and automatic switch control circuits and line marking circuits governed by the line and cut-off relays.

In accordance with another feature of the invention the line and cut-off relays and the automatic switch control and line marking circuits in the line circuit are so connected and arranged that the automatic switches in the system are controlled thereby to set up, by way of the line, outgoing call connections from the substations 25 associated with the line, incoming call connections to the subscriber substations associated with the line, and reverting call connections between two of the subscriber substations associated with the line, and that the line is marked as busy to the remainder of the automatic switches not employed in a connection including the line while the connection including the line is set up, and that the line is marked as busy to the automatic switches in the event a fault appears thereon.

40 In accordance with another feature of the invention the line circuit also comprises means responsive to the creation of a calling condition on the line for causing the line relay to be operated to the first position, means responsive to the seizure of the line by one of the automatic switches for causing the cut-off relay to be operated, means controlled by the operation of the cut-off relay for causing the line relay to be operated to the second position, means for releasing the one automatic switch, means responsive to the release of the one automatic switch for causing the cut-off relay to be restored, and means for causing the line relay to remain operated to the second position subsequent to the restoration of the cut-off 45 relay in the event a calling condition remains on the line. Furthermore, means is provided which is controlled, when the line relay is operated to the second position and the cut-off relay is restored, for marking the line as busy to the 50 automatic switches.

In accordance with a further feature of the invention a telephone system is provided which comprises a line, a plurality of subscriber substations associated with the line, a number of 55 automatic switches having access to the line, and a line circuit of the type described associated with the line. Further the telephone system comprises means responsive to the initiation of a call at a calling one of the substations for creating a calling condition on the line, means responsive to the creation of a calling condition on the line for causing the line relay to be operated to the first position, means controlled by the operation of the line relay to the first position for causing an idle one of the automatic

switches to seize the line, means responsive to the seizure of the line by the one automatic switch for causing the cut-off relay to be operated, and means controlled by the operation of the cut-off relay for causing the line relay to be operated to the second position. Furthermore, the telephone system comprises impulse responsive means operative to cause ringing current to be projected by way of the one automatic switch over the line subsequent to the termination of the calling condition thereon and to cause the cut-off relay to remain operated, means responsive to the answering of the call at a called one of the substations for causing the one automatic switch to be released and for creating a new calling condition on the line, means responsive to the release of the one automatic switch for causing the cut-off relay to be released, means responsive to the creation of the new calling condition on the line for causing the line relay to remain operated to the second position subsequent to the restoration of the cut-off relay, and means controlled, when the line relay is operated to the second position and the cut-off relay is restored, for marking the line as busy to the automatic switches.

In accordance with a further feature of the invention a telephone system is provided which comprises a line, a number of finder and connector switches having access to the line, and a line circuit of the type described associated with the line. Also, the telephone system comprises means controlled by the operation of the line relay to the first position for marking the line as busy to the connector switches and for causing an idle one of the connector switches to seize the line, and additional finder and connector switch control circuits and additional line marking circuits governed by the line and cut-off relays.

In accordance with a further feature of the invention a combined line and cut-off relay is provided which is adapted for use in a telephone line circuit, and comprises, in combination, a support, line and cut-off magnets carried by the support and each provided with an energizing winding, a movable contact actuating member operatively associated with the line magnet and having a normal position, a movable contact actuating member operatively associated with the cut-off magnet and having a normal position, contacts respectively associated with the members, mechanical means for limiting the movement of the first-mentioned member away from its normal position, and means controlled by the energization of the cut-off magnet winding for controlling the release of the mechanical means. The mechanical means is so constructed and arranged that the first-mentioned member is moved a limited distance away from its normal position in response to the energization of the line magnet winding prior to the energization of the cut-off magnet winding, and that the first-mentioned member is moved a further distance away from its normal position in response to the energization of the line magnet winding subsequent to the energization of the cut-off magnet winding.

Further features of the invention pertain to the particular arrangement of the circuit elements thereof, whereby the above-outlined and additional features are attained.

The novel features believed to be characteristic of the invention are set forth with particularity in the appended claims. The invention, both as to its organization and method of operation, together with further objects and advan-

tages thereof, will best be understood by reference to the following specification taken in connection with the accompanying drawings in which Figs. 1 and 2 taken together illustrate diagrammatically a telephone system including two improved forms of line circuits and embodying the present invention; Fig. 3 is a front elevational view of a combined line and cut-off relay adapted to be incorporated into each of the line circuits shown in Fig. 1 and embodying the present invention; Fig. 4 is a side elevational view, partly broken away, of the relay shown in Fig. 3; Fig. 5 illustrates diagrammatically the arrangement of the switch springs associated with the combined line and cut-off relay when it is incorporated in the line circuit shown on the left-hand side of Fig. 1; and Fig. 6 illustrates diagrammatically the arrangement of the switch springs associated with the combined line and cut-off relay when it is incorporated in the line circuit shown on the right-hand side of Fig. 1.

Referring now more particularly to Figs. 1 and 2 of the drawings, the telephone system there illustrated comprises an exchange having a plurality of subscriber lines including the subscriber lines 150 and 160 terminating thereat, and provided with a plurality of finder-connector links including the link 100 for setting up connections between the various subscriber lines. Also a distributor 103 is provided for assigning idle ones of the links to the use of calling ones of the subscriber lines; and a number of reverting call switches, including the reverting call switch 200, are provided for the purpose of projecting code ringing current over a subscriber line when a reverting call is initiated thereon. More specifically, the exchange has an ultimate capacity of one hundred lines, and the number of links is determined by the amount of traffic which the exchange is required to handle, usually ten links being adequate to render satisfactory service.

Each of the links may be identical to the link 100 which comprises a finder portion or switch 101 and a connector portion or switch 102, each having access to each subscriber line in the system. The finder switch and the connector switch included in each link may be one of any of a number of well-known types. However, it is preferable that each of these switches includes a switching mechanism of the Strowger type and the usual control apparatus therefor, the wipers of the switching mechanism included in the finder switch 101 being illustrated at 180, 181 and 182, and the wipers of the switching mechanism included in the connector switch 102 being illustrated at 183, 184, and 185. Also the connector switch 102 comprises impulse responsive apparatus of any desired type for projecting code ringing current over an idle called subscriber line after it has been seized by the switching mechanism included therein, which is so connected and arranged that a divided ringing circuit may be employed in the system. The distributor 103 may be one of any of a number of well-known types. However, it is preferable that the distributor 103 is of the preselective type, such that an idle link is selected to be assigned to the use of a calling line prior to the initiation of a call on the line.

At least a number of the subscriber lines terminating at the exchange are of the party type, the subscriber lines 150 and 160 being party lines, each serving a number of subscriber substations, respectively, including the subscriber substations

tions is provided with a telephone instrument, a dial mechanism, and a ringer. The subscriber substations associated with each party line are arranged in two groups, the ringer at each substation in the first group being connected between one line conductor of the subscriber line and ground, and the ringer at each substation in the second group being connected between the other line conductor of the subscriber line and ground, whereby a divided ringing circuit is employed in the system.

A line circuit is individually associated with each subscriber line in the system, the line circuit 104 being individually associated with the subscriber line 150, and the line circuit 105 being individually associated with the subscriber line 160. As previously noted, two different forms of line circuits may be alternatively employed in the system, the line circuit 104 being a line circuit of the first form, and the line circuit 105 being a line circuit of the second form. Each of the line circuits of the first form may be identical to the line circuit 104 which comprises a combined line and cut-off relay of the construction shown in Figs. 3 and 4 including a line magnet or relay R120, a cut-off magnet or relay R110, and a switch spring assembly of the construction and arrangement shown in Fig. 5. Each of the line circuits of the second form may be identical to the line circuit 105 which comprises a combined line and cut-off relay of the construction shown in Figs. 3 and 4 including a line magnet or relay R130, a cut-off magnet or relay R140, and a switch spring assembly of the construction and arrangement shown in Fig. 6.

Each of the reverting call switches may be identical to the reverting call switch 200 which comprises two minor switches 280 and 290, a line relay R230, a hold relay R240, two transfer relays R260 and R270, a ring cut-off relay R255, a switching-through relay R220, two control relays R210 and R250, the control and controlled circuits therefor, and a transformer 201. The minor switch 280 comprises two rotary switches 281 and 282 provided with contact banks 284 and 286, respectively, and associated wipers 283 and 285, respectively, a rotary magnet M236 for simultaneously rotating the wipers of the rotary switches 281 and 282, and a release magnet M237 for releasing the wipers of the rotary switches 281 and 282 and for causing these wipers to be returned to their normal positions. Also two switch springs 234 are associated with the wipers of the rotary switches 281 and 282, which are actuated into engagement when these wipers are rotated by the rotary magnet M236 away from their normal positions. The minor switch 290 comprises two rotary switches 291 and 292 provided with contact banks 294 and 296, respectively, and associated wipers 293 and 295, respectively, a rotary magnet M238 for simultaneously rotating the wipers of the rotary switches 291 and 292, and a release magnet M239 for releasing the wipers of the rotary switches 291 and 292 and for causing these wipers to be returned to their normal positions. Also two switch springs 235 are associated with the wipers of the rotary switches 291 and 292, which are actuated into engagement when these wipers are rotated by the rotary magnet M238 away from their normal positions. Also it is noted that the reverting call switch 200 is connected and arranged to project code ringing current over a calling subscriber line by way of the trunk line 170 when a connection is established therebetween by way of an operated one of the links, in such a manner that

75 A, B and C, D. Each of the subscriber substations

a divided ringing circuit may be employed in the system.

As best shown in Figs. 3 and 4 of the drawings, the combined line and cut-off relay which is incorporated in each of the forms of the line circuits 104 and 105 employed in the system comprises a supporting plate 300 provided with an outwardly extending flange 301 to which a line magnet core 302 and a cut-off magnet core 303 are respectively secured by two screws 304 and 305, the cores 302 and 303 being arranged in spaced parallel relationship with respect to each other and to the body portion of the plate 300. The body portion of the supporting plate 300 is provided with two spaced apart tabs 306 and 307 arranged adjacent the pole faces of the cores 302 and 303, respectively. A supporting bracket 308 carrying a pivot pin 309 is suitably secured to the tab 306; and a supporting bracket 310 carrying a pivot pin 311 is suitably secured to the tab 307. An armature 312 is pivotally supported on the pivot pin 309 adjacent the pole face of the core 302; and an armature 313 is pivotally supported on the pivot pin 311 adjacent the pole face of the core 303. The armature 312 is provided with a downwardly extending arm 314 having a rearwardly projecting finger 315 on the outer end thereof extending through an aperture 316 formed in the supporting plate 300; and the armature 313 is provided with a downwardly extending arm 317 having a rearwardly projecting finger 318 extending through an aperture 319 formed in the supporting plate 300. A switch spring assembly 320 comprising a plurality of individual switch springs suitably insulated from each other and from the supporting plate 300 is secured to the rear side of the supporting plate, and cooperates with an insulating button 321 carried by the finger 315 in such a manner that the individual switch springs in this switch spring assembly are actuated into engagement and disengagement with each other in a predetermined manner, when the armature 312 is rotated about the pivot pin 309. Also a switch spring assembly, not shown, comprising a plurality of individual switch springs suitably insulated from each other and from the supporting plate 300 is secured to the rear side of the supporting plate, and cooperates with an insulating button carried by the finger 318 in such a manner that the individual switch springs in this switch spring assembly are actuated into engagement and disengagement with each other in a predetermined manner, when the armature 313 is rotated about the pivot pin 311. A blocking or latching spring 322 is secured, intermediate the ends thereof, to the front side of the supporting plate 300 in a position disposed between the cores 302 and 303 by an arrangement comprising an insulating bushing 323 and a screw 324. One end 325 of the latching spring 322 is positioned in a recess 326 formed in the edge of the flange 301 in order to retain the latching spring in place, and the other end 327 of the latching spring 322 extends to a position adjacent the armatures 312 and 313. The end 327 of the latching spring 322 is bifurcated; comprising two spaced apart fingers 328 and 329 cooperating with two projecting lugs 330 and 331, respectively, carried by the armatures 312 and 313. The finger 328 constitutes a latching finger and is so constructed and arranged that it normally projects into the path of movement of the lug 330 carried by the armature 312 when this armature is rotated in a clockwise direction, as viewed in Fig. 4, about the pivot pin 309, thereby

to permit only a limited rotational movement of the armature 312 about the pivot pin 309. The finger 329 constitutes a tripping finger and is so constructed and arranged that it normally projects into the path of movement of the lug 331 carried by the armature 313 when this armature is rotated in a clockwise direction, as viewed in Fig. 4, about the pivot pin 311. When the armature 313 is rotated in a clockwise direction about the pivot pin 311 the lug 331 carried thereby engages the tripping finger 329 and bends the end 327 of the latching spring 322 away from the supporting plate 300, thereby to move the latching finger 328 out of the path of movement of the lug 330 carried by the armature 312 in order to allow further rotational movement of the armature 312 in a clockwise direction about the pivot pin 309. From the foregoing description of the construction and arrangement of the latching spring 322 it will be understood that when the armature 312 is rotated in a clockwise direction about the pivot pin 309 it is initially rotated only a predetermined distance, at which time the latching finger 328 arrests further rotation thereof. Subsequently, when the armature 313 is rotated in a clockwise direction about the pivot pin 311 the tripping finger 329 releases the latching finger 328, thereby to permit further rotation of the armature 312 in a clockwise direction about the pivot pin 309.

The line magnet core 302 is provided with a winding arrangement which is effective, when energized, to attract the armature 312, thereby to rotate this armature in a clockwise direction about the pivot pin 309; and the cut-off magnet core 303 is provided with a winding arrangement which is effective, when energized, to attract the armature 313, thereby to rotate this armature in a clockwise direction about the pivot pin 311. Thus it will be understood that, when the winding arrangement of the line magnet is energized, the armature 312 is rotated in a clockwise direction about the pivot pin 309 a predetermined distance, and then subsequently, when the winding arrangement of the cut-off magnet is energized to rotate the armature 313 in a clockwise direction about the pivot pin 311, the armature 312 is rotated an additional distance in the clockwise direction about the pivot pin 309. Also, it will be understood that the initial rotation of the armature 312 is effective to cause a predetermined actuation of the switch spring assembly 320 associated therewith, and the further rotation thereof is effective to cause a further predetermined actuation of the switch spring assembly 320; and the rotation of the armature 313 is effective to cause a predetermined actuation of the switch spring assembly 320 associated therewith. Thus, the line magnet 302 is of the two-step type.

Referring now more particularly to Fig. 5 of the drawings, it will be observed that the switch spring assembly associated with the line and cut-off magnets R120 and R110, respectively, corresponding to the switch spring assembly incorporated in the line circuit 104, is so constructed and arranged that, when the line magnet R120 is energized, the armature indicated at 312a is rotated in a clockwise direction about the pivot pin 309a a predetermined distance, thereby to move the switch spring RA128 into engagement with the associated switch spring in order to close these X contacts, and to move the switch spring RA121 into engagement with the switch spring RC122 in order to close these X contacts, at which time the outer end of the armature 312a engages the latching finger 328a. 75

- Subsequently, when the cut-off magnet R110 is energized the armature indicated at 313a is rotated in a counterclockwise direction about the pivot pin 311a, thereby to move the switch springs 5 RA112 and RC113 into disengagement, to move the switch springs RA112 and RC114 into engagement, to move the switch springs RA115 and RA116 into engagement, and then to move the switch springs RA116 and RC117 into disengagement, and finally to move the switch spring 10 RA111 and the associated switch spring into disengagement in order to open these Y contacts. Also, when the armature 313a is rotated in a counterclockwise direction about the pivot pin 15 311a the tripping finger 329a is engaged by the outer end of the armature 313a, thereby to release the latching finger 328a. The armature 312a is then rotated a further distance in the clockwise direction about the pivot pin 309a, thereby to 20 move the switch springs RA123 and RC124 into disengagement, to move the switch springs RA125 and RA126 into engagement, and then to move the switch springs RA126 and RC127 into disengagement. 25 Referring now more particularly to Fig. 6 of the drawings, it will be observed that the switch spring assembly associated with the line and cut-off magnets R130 and R140, respectively, corresponding to the switch spring assembly incorporated in the line circuit 105, is so constructed and arranged that, when the line magnet R130 is energized, the armature indicated at 312b is rotated in a clockwise direction about the pivot pin 309b a predetermined distance, thereby to 30 move the switch springs RA133 and RC133 into disengagement in order to open these X contacts, to move the switch springs RA133 and RC134 into engagement in order to close these X contacts, to move the switch springs RA131 and 35 RC132 into engagement in order to close these X contacts, and to move the switch spring RA137 into engagement with the associated switch spring in order to close these X contacts, at which time the outer end of the armature 312b engages the latching finger 328b. Subsequently, when the cut-off magnet R140 is energized the armature indicated at 313b is rotated in a counterclockwise direction about the pivot pin 311b, thereby to move the switch springs RA142 and 40 RC143 into engagement, to move the switch springs RA144 and RC145 into engagement, to move the switch springs RA146 and RA147 into engagement, and then to move the switch springs RA146 and RC148 into disengagement, to move the switch spring RA149 and the associated switch spring into disengagement, to move the switch spring RA140' and the associated switch spring into disengagement, and finally to move the switch spring RA141 and the associated 45 switch spring into disengagement in order to open these Y contacts. Also when the armature 313b is rotated in a counterclockwise direction about the pivot pin 311b, the tripping finger 329b is engaged by the outer end of the armature 313b, thereby to release the latching finger 328b. The armature 312b is then rotated a further distance 50 in the clockwise direction about the pivot pin 309b, thereby to move the switch spring RA138 and the associated switch spring into disengagement, to move the switch spring RA139 and the associated switch spring into engagement, to move the switch spring RA130' and the associated switch spring into disengagement, and to move the switch springs RA136 and RC135 into 55 disengagement. 60

The connection and arrangement of the system will best be understood from a consideration of the following description, with reference to Figs. 1 and 2 of the drawings, of the operation of the apparatus incorporated therein to set up the 5 different connections between the various subscriber lines.

A call which is to be extended from the subscriber substation A to the subscriber substation C is first initiated at the substation A by removing the receiver of the telephone instrument thereat from its hook, thereby to complete a bridge path at the telephone instrument at the substation A between the line conductors C151 and C152 of the subscriber line 150 extending to 10 the substation A. When this bridge path is completed between the line conductors of the subscriber line 150 a bridge circuit is completed for energizing in series the upper and lower windings of the line magnet R120 in the line circuit 104 20 individually associated with the subscriber line 150, which extends from battery at the upper winding of R120 by way of the upper winding of R120, RA111, C151, the bridge path at the substation A between C151 and C152, 25 RA111, RA116, and the lower winding of R120 to ground. When energized over the above-traced circuit the line magnet R120 partially operates, thereby to close the X contact associated with the switch springs RA121 and RC122 and to close 30 the X contact associated with the spring RA128 and the associated switch spring, further actuation of the switch springs associated with the line magnet R120 being positively prevented, at this time, by the mechanical locking arrangement 35 under the control of the cut-off magnet R110. More particularly, the line magnet R120 completes, at RA128, a path for applying ground potential to the start conductor C190 extending into the distributor 103, this path extending from 40 ground, at RA126, by way of RC127, RA128, and C191 to the start conductor C190. This application of ground potential to the start conductor C190 initiates the operation of the distributor 45 103, and causes the distributor to operate and assign the previously selected idle link to the use of the calling subscriber line 150. Assuming that the illustrated link 100 is assigned by the distributor 103 to the use of the calling subscriber line 150, the distributor also marks with 50 ground potential by way of the conductor C193 the level in the contact bank of the Strowger mechanism included in the finder switch 101, wherein the calling subscriber line 150 terminates. Also the line magnet R120 completes, 55 at RA121 and RC122, a path for applying battery potential to the control conductor C153, this path extending from battery at the winding of the cut-off magnet R110 by way of the winding of R110, RA123, RC124, RC122, and RA121 to 60 the control conductor C153. This application of battery potential to the control conductor C153 marks the radial position of the contact set in the level in the contact bank of the Strowger mechanism included in the finder switch 101, 65 wherein the calling subscriber line 150 terminates. The Strowger mechanism included in the finder switch 101 then operates to move the wipers 180, 181, and 182 thereof in the vertical direction to the level wherein the calling subscriber line 150 terminates. This Strowger mechanism then operates to move the wipers thereof in the radial direction to the radial position of the contact set wherein the calling subscriber line 150 terminates, at which time the wipers 180 and 182 70

thereof engage the contacts terminating the line conductors C151 and C152, respectively, and the wiper 181 engages the contact terminating the control conductor C153 of the calling subscriber line 150. The presence of battery potential upon the control conductor C153 completes a circuit for energizing a relay in the finder switch 101 operative to arrest further operation of the Strowger mechanism included therein, which relay also operates to complete a path for applying ground potential to the wiper 181. This application of ground potential to the wiper 181 completes a circuit for energizing the cut-off magnet R110, this circuit extending from the grounded wiper 181 by way of the contact terminating the control conductor C153, RA121, RC122, RC124, RA123, and the winding of R110 to battery. Also this application of ground potential to the wiper 181 completes a path for applying ground potential to the control conductor C154 of the subscriber line 150 extending to the contact banks of the Strowger mechanisms included in the connector switches of the links having access thereto, thereby to mark the subscriber line 150 as busy to the connector switches of these links. This path extends from the grounded control conductor C153 by way of RA121 and RC122 to the control conductor C154.

When energized over the above-traced circuit the cut-off magnet R110 operates to complete, at RA115 and RA116, an obvious holding circuit for energizing in series the upper and lower windings of the line magnet R120, and interrupts, at RA116 and RC117, and at RA111, points in the original bridge circuit for energizing the windings of the line magnet R120, thereby to free the line conductors C151 and C152 of the subscriber line 150 of impedance elements. Finally the cut-off magnet R110 completes, at RA112 and RC114, a holding circuit for energizing the winding thereof of extending from the grounded control conductor C153 by way of RA121, RC122, RA122, RC114, and the winding of R110 to battery. Also, upon operating, the cut-off magnet R110 releases the locking arrangement associated with the armature of the line magnet R120, thereby to allow the line magnet R120 to operate fully. Upon fully operating, the line magnet R120 interrupts, at RA123 and RC124, a point in the original circuit for energizing the winding of the cut-off magnet R110, and interrupts, at RA126 and RC127, a point in the path for applying ground potential to the start conductor C190 extending to the distributor 103. When ground potential is removed from the start conductor C190 the distributor 103 operates to select an idle link in the group of links to be assigned to the use of the next calling subscriber line. When the finder switch 101 seizes the calling subscriber line 150, the connector switch 102 operates to condition the Strowger mechanism therein to be responsive to dialed digits.

The subscriber at the substation A then dials the first digit of the directory number of the called subscriber line at the dial mechanism thereat, thereby to transmit a first series of impulses over the loop circuit extending by way of the subscriber line 150 between the substation A and the connector switch 102. Impulse responsive apparatus in the connector switch 102 operates in response to this first series of impulses in order to cause the wipers 183, 184, and 185 of the Strowger mechanism included therein to be moved in the vertical direction to the level in the contact bank therein, wherein the called sub-

scriber line 160 is terminated. The subscriber at the substation A then dials the second digit of the directory number of the called subscriber line at the dial mechanism thereat, thereby to transmit a second series of impulses by way of the previously mentioned loop circuit to the connector switch 102 in order to cause the wipers noted of the Strowger mechanism included therein to be moved in the radial direction to the position of the contact set in the contact bank therein, wherein the called subscriber line 160 is terminated. The subscriber at the substation A then dials the third digit of the directory number of the called substation C at the dial mechanism thereat, thereby to transmit a third series of impulses by way of the previously mentioned loop circuit to the connector switch 102 in order to cause the connector switch to select a corresponding code ringing current to be projected over the called subscriber line 160 in the event this subscriber line is idle.

At this time the wipers 183 and 185 engage the contacts in the contact bank terminating the line conductors C161 and C162, respectively, and the wiper 184 engages the contact in the contact bank terminating the control conductor C163 of the called subscriber line 160. At this time ground potential appears upon the control conductor C163 in the event the called subscriber line 160 is busy. On the other hand, battery potential appears upon the control conductor C163 in the event the called subscriber line 160 is idle.

Assuming that the called subscriber line 160 is busy, ground potential derived in the line circuit 105 appears upon the control conductor C163 thereof, thereby to complete a path for energizing a busy relay included in the connector switch 102, which busy relay operates to cause busy tone current to be returned over the loop circuit extending to the calling subscriber substation A, in the usual manner. The production of busy tone in the receiver of the telephone instrument at the calling substation A indicates to the subscriber thereat that the desired connection cannot immediately be had due to the busy condition of the called subscriber line 160. The subscriber at the calling substation A then releases the operated link 100 and the line circuit 104 by replacing the receiver of the telephone instrument at the substation A upon its hook. The exact manner in which these operated pieces of apparatus are released is described in detail hereinafter.

Assuming that the called subscriber line 160 is idle, battery potential appears upon the control conductor C163 thereof, this battery potential being derived at the winding of the cut-off magnet R140 and extending therefrom by way of the winding of R140, RA130', RC133, and RA133 to the control conductor C163. This application of battery potential to the control conductor C163 completes a path for short-circuiting the busy relay included in the connector switch 102, thereby to cause the connector switch 102 to operate and project ringing current of the previously selected code over the called subscriber line 160 in order to cause the ringer at the substation C to operate in a characteristic manner. This characteristic operation of the ringer at the substation C indicates to the subscriber thereat that the substation C is the called substation. Also, a switch-through relay in the connector switch 102 operates to apply direct ground potential to the wiper 184. This application of direct ground potential to the

wiper 184 completes a circuit for energizing the cut-off magnet R140, this circuit extending from the grounded wiper 184 by way of C163, RA133, RC133, RA130', and the winding of R140 to battery. When energized over the above-traced circuit the cut-off magnet R140 operates to complete, at RA144 and RC145, a holding circuit for energizing the winding thereof, this circuit extending from the grounded control conductor C163 by way of RA144, RC145, and the winding of R140 to battery. Also, upon operating, the cut-off magnet R140 completes, at RA146 and RA147, a holding circuit for energizing the line magnet R130, this circuit extending from ground, at the lower winding of R130, by way of the lower winding of R130, RA146, RA147, and the upper winding of R130 to battery. Also, upon operating, the cut-off magnet R140 releases the locking arrangement associated with the armature of the line magnet R130, thereby to allow the line magnet R130 to operate fully. When energized over the above-traced circuit the line magnet R130 fully operates to complete, at RA131 and RC132, a path for applying ground potential to the control conductor C164 of the subscriber line 160 extending to the contact banks of the Strowger mechanisms included in the finder switches of the links having access thereto, thereby to mark the subscriber line 160 as busy, this path extending from the grounded control conductor C163 by way of RC143, RA142, RC132, and RA131 to the control conductor C164. The subscriber at the substation C then answers the call by removing the receiver of the telephone instrument thereat from its hook, thereby to cause the connector switch 102 to operate in order to interrupt the projection of ringing current over the called subscriber line and to complete an established communication connection between the calling subscriber line 150 and the called subscriber line 160 by way of the operated link 100.

Assuming that the release of this established connection is under the control of the last subscriber to replace the receiver of the telephone instrument at his substation upon its hook, when the last subscriber at one of the substations replaces the receiver of the telephone instrument thereat upon its hook the operated link 100 is released in the usual manner, thereby to interrupt the established connection extending between the subscriber lines 150 and 160. When the link 100 is released ground potential therein is removed from the wiper 181, thereby to interrupt the previously traced holding circuit for energizing the winding of the cut-off magnet R110. The cut-off magnet R110 then restores, thereby to interrupt, at RA112 and RC114, a further point in the holding circuit for energizing the winding thereof, and to interrupt, at RA115 and RA116, the previously traced circuit for energizing in series the upper and lower windings of the line magnet R120. Also, upon restoring, the cut-off magnet R110 prepares, at RA111, and at RA116 and RC117, the previously traced bridge circuit for energizing the windings of the line magnet R120. The line magnet R120 then restores to complete, at RA123 and RC124, the previously traced path for applying battery potential, at the winding of the cut-off magnet R110, to the control conductor C154 extending to the contact banks of the Strowger mechanisms included in the connector switches of the links having access thereto, thereby to mark the subscriber line 150 as idle. Also the line magnet R120 prepares, at RA126 and RC127, a point in the previously traced path

for applying ground potential to the start conductor C190, and interrupts, at RA128, a point in this path. Finally, the line magnet R120 interrupts, at RA121 and RC122, the connection between the control conductor C153 and C154, thereby to interrupt the paths for applying ground or battery potential to the control conductor C153 extending to the contact banks of the Strowger mechanisms included in the finder switches of the links having access thereto, in order to mark the subscriber line 150 as idle. At this time the subscriber line 150 is marked as idle to the finder and connector switches of the links having access thereto, and the line circuit 104 is completely released. 15

Also, when the link 100 is released ground potential therein is removed from the wiper 184, thereby to interrupt the previously traced holding circuit for energizing the winding of the cut-off magnet R140. The cut-off magnet R140 then restores, thereby to interrupt, at RA144 and RC145, a further point in the holding circuit for energizing the winding thereof, to interrupt, at RA146 and RA147, the holding circuit for energizing in series the upper and lower windings of the line magnet R130, and prepares, at RA141, and at RA146 and RC148, points in a bridge circuit for energizing the windings of the line magnet R130. The line magnet R130 then restores to complete, at RA130', and at RA133 and RC133, the previously traced path for applying battery potential, at the winding of the cut-off magnet R140, to the control conductor C163 extending to the contact banks of the Strowger mechanisms included in the connector switches of the links having access thereto, thereby to mark the subscriber line 160 as idle. Also the line magnet R130 interrupts, at RA131 and RC132, the connection between the control conductors C163 and C164, thereby to interrupt the path for applying ground or battery potential to the control conductor C164 extending to the contact banks of the Strowger mechanisms included in the finder switches of the links having access thereto, thereby to mark the subscriber line 160 as idle. At this time the subscriber line 160 is marked as idle to the finder and connector switches of the links having access thereto, and the line circuit 105 is completely released. 35

A call which is to be extended from the subscriber substation C to the subscriber substation A is first initiated at the substation C by removing the receiver of the telephone instrument thereat from its hook, thereby to complete a bridge path at the telephone instrument at the substation C between the line conductors C161 and C162 of the subscriber line 160 extending to the substation C. When this bridge path is completed between the line conductors of the subscriber line 160 a bridge circuit is completed for energizing in series the upper and lower windings of the line magnet R130 in the line circuit 105 individually associated with the subscriber line 160, which extends from battery at the upper winding of R130 by way of the upper winding of R130, RA141, C161, the bridge path at the substation C between C161 and C162, C162, RC148, RA146, and the lower winding of R130 to ground. When energized over the above-traced circuit the line magnet R130 partially operates, thereby to close the "X" contact associated with the switch springs RA131 and RC132, to close the "X" contact associated with the switch springs RA133 and RC134, to close the "X" contact associated with the switch spring RA137 and the associated switch 70 75

spring, and to open the "X" contact associated with the switch springs RA133 and RC133. Further actuation of the switch springs associated with the line magnet R130 is positively prevented, 5 at this time, by the mechanical locking arrangement under the control of the cut-off magnet R140. More particularly, the line magnet R130 completes, at RA137, a path for applying ground potential to the start conductor C190 extending 10 into the distributor 103, this path extending from ground, at RA137, by way of RA138, and C192 to the start conductor C190. This application of ground potential to the start conductor C190 initiates the operation of the distributor 103, and 15 causes the distributor to operate and assign the previously selected idle link to the use of the calling subscriber line 160. Assuming that the illustrated link 100 is assigned by the distributor 103 to the use of the calling subscriber line 160, 20 the distributor also marks with ground potential, by way of the conductor C193, the level in the contact bank in the Strowger mechanism included in the finder switch 101 wherein the calling subscriber line 160 terminates. Also the line 25 magnet R130 completes, at RA131 and RC132, a path for applying battery potential to the control conductor C164, this path extending from battery, at the winding of the cut-off magnet R140, by way of the winding of R140, RA130', RC132, and 30 RA131, to the control conductor C164. This application of battery potential to the control conductor C164 marks the radial position of the contact set in the level in the contact bank of the Strowger mechanism included in the finder 35 switch 101, wherein the calling subscriber line 160 terminates. Further the line magnet R130 completes, at RA133 and RC134, a path for applying ground potential to the control conductor C163 extending to the contact banks of the 40 Strowger mechanisms included in the connector switches of the links having access thereto, thereby to mark the subscriber line 160 as busy immediately, and prior to the time the finder switch 101 of the link 100 operates to seize this subscriber line, this path extending from ground, at 45 RA136, by way of RC135, RC134, and RA133, to the control conductor C163. Finally, the line magnet R130 interrupts, at RA133 and RC133, a point in the previously traced connection between 50 the control conductor C163 and the winding of the cut-off magnet R140, thereby to prevent the application of ground potential to the control conductor C163 from causing premature energization of the cut-off magnet R140 prior to the time the finder switch 101 operates to seize the calling subscriber line 160.

The Strowger mechanism included in the finder switch 101 then operates to move the wipers 180, 181, and 182 thereof in the vertical direction to 55 the level wherein the calling subscriber line 160 terminates. This Strowger mechanism then operates to move the wipers thereof in the radial direction to the radial position of the contact set wherein the calling subscriber line 160 terminates, 60 at which time the wipers 180 and 182 thereof engage the contacts terminating the line conductors C161 and C162, respectively, and the wiper 181 engages the contact terminating the control conductor C164 of the calling subscriber 65 line 160. The presence of battery potential upon the control conductor C164 completes a circuit for energizing a relay in the finder switch 101 operative to arrest further operation of the Strowger mechanism included therein, which 70 relay also operates to complete a path for applying

ground potential to the wiper 181. This application of ground potential to the wiper 181 completes a circuit for energizing the cut-off magnet R140, this circuit extending from the grounded wiper 181 by way of the contact terminating the control conductor C164, RA131, RC132, RA130', and the winding of R140 to battery.

When energized over the above-traced circuit the cut-off magnet R140 operates to complete, at RA142 and RC143, and at RA144 and RC145, a holding circuit for energizing the winding thereof, this circuit extending from the grounded control conductor C164 by way of RA131, RC132, RA142, RC143, RA144, RC145, and the winding of R140 to battery. Also the cut-off magnet R140 completes, at RA142 and RC143, a connection between the control conductors C163 and C164, thereby to complete a path for applying ground potential appearing upon the control conductor C164 to the control conductor C163 extending to 20 the contact banks of the Strowger mechanisms included in the connector switches of the links having access thereto, this path extending from the control conductor C164 by way of RA131, RC132, RA142, and RC143, to the control conductor C163. This path for applying ground potential to the control conductor C163 causes the subscriber line 160 to be marked as busy to the connector switches of the links having access thereto after the line magnet R130 operates 30 completely to interrupt, at RA136 and RC135, the previously traced path for applying ground potential to the control conductor C163. Also the cut-off magnet R140 completes, at RA146 and RA147, the holding circuit for energizing in series 35 the upper and lower windings of the line magnet R130, this circuit extending from ground, at the lower winding of R130, by way of the lower winding of R130, RA146, RA147, and the upper winding of R130 to battery. Finally, the cut-off magnet R140 interrupts, at RA146 and RC148, and at RA141, points in the original bridge circuit for energizing the windings of the line magnet R130, thereby to free the calling subscriber line 160 of impedance elements. Also, upon operating, 40 the cut-off magnet R140 releases the locking arrangement associated with the armature of the line magnet R130, thereby to allow the line magnet R130 to operate fully. Upon fully operating, the line magnet R130 interrupts, at RA130', a 45 point in the original circuit for energizing the winding of the cut-off magnet R140, and interrupts, at RA138, a point in the path for applying ground potential to the start conductor C190 extending to the distributor 103. When ground potential is removed from the start conductor C190 the distributor 103 operates to select an idle link in the group of links to be assigned to the use of the next calling subscriber line. Also, upon operating, the line magnet R130 interrupts, at 50 RA136 and RC135, a point in the original path for applying ground potential, at RA136, to the control conductor C163 extending to the contact banks of the Strowger mechanisms included in the connector switches of the links having access 55 thereto, ground potential being applied to the control conductor C163 at this time by way of the previously traced path from the control conductor C164. When the finder switch 101 seizes the calling subscriber line 160, the connector switch 102 operates to condition the Strowger mechanism therein to be responsive to dialed digits.

The subscriber at the substation C then dials the first digit of the directory number of the 75

called subscriber line at the dial mechanism thereat, thereby to transmit a first series of impulses over the loop circuit extending by way of the subscriber line 160 between the substation C and the connector switch 102. Impulse responsive apparatus in the connector switch 102 operates in response to this first series of impulses in order to cause the wipers 183, 184, and 185 of the Strowger mechanism included therein to be moved in the vertical direction to the level in the contact bank therein, wherein the called subscriber line 150 is terminated. The subscriber at the substation C then dials the second digit of the directory number of the called subscriber line 150 at the dial mechanism thereat, thereby to transmit a second series of impulses by way of the previously mentioned loop circuit to the connector switch 102 in order to cause the wipers noted of the Strowger mechanism included therein to be moved in the radial direction to the position of the contact set in the contact bank therein, wherein the called subscriber line 150 is terminated. The subscriber at the substation C then dials the third digit of the directory number of the called substation A at the dial mechanism thereat, thereby to transmit a third series of impulses by way of the previously mentioned loop circuit to the connector switch 102 in order to cause the connector switch to select a corresponding code ringing current to be projected over the called subscriber line 150 in the event this subscriber line is idle.

At this time the wipers 183 and 185 engage the contacts in the contact bank terminating the line conductors C151 and C152, respectively, and the wiper 184 engages the contact in the contact bank terminating the control conductor C154 of the called subscriber line 150. At this time ground potential appears upon the control conductor C154 in the event the called subscriber line 150 is busy. On the other hand, battery potential appears upon the control conductor C154 in the event the called subscriber line 150 is idle.

Assuming that the called subscriber line 150 is busy, ground potential derived in the line circuit 104 appears upon the control conductor C154 thereof, thereby to complete a path for energizing the busy relay included in the connector switch 102, which busy relay operates to cause busy tone current to be returned over the loop circuit extending to the calling subscriber substation C, in the usual manner. The production of busy tone in the receiver of the telephone instrument at the calling substation C indicates to the subscriber thereat that the desired connection cannot immediately be had due to the busy condition of the called subscriber line 150. The subscriber at the calling substation C then releases the operated link 100 and the line circuit 105 by replacing the receiver of the telephone instrument at the substation C upon its hook. The exact manner in which these operated pieces of apparatus are released is described in detail hereinafter.

Assuming that the called subscriber line 150 is idle, battery potential appears upon the control conductor C154 thereof, this battery potential being derived at the winding of the cut-off magnet R110 and extending therefrom by way of the winding of R110, RA123, and RC124 to the control conductor C154. This application of battery potential to the control conductor C154 completes a path for short-circuiting the busy relay included in the connector switch 102, thereby to cause the connector switch 102 to operate and project ring-

5 called subscriber line 150 in order to cause the ringer at the substation A to operate in a characteristic manner. This characteristic operation of the ringer at the substation A indicates to the subscriber thereat that the substation A is the called substation. Also, the switch-through relay in the connector switch 102 operates to apply direct ground potential to the wiper 184. This application of direct ground potential to the wiper 184 completes a circuit for energizing the cut-off 10 magnet R110, this circuit extending from the grounded wiper 184 by way of C154, RC124, RA123, and the winding of R110 to battery.

When energized over the above-traced circuit the cut-off magnet R110 operates to complete, at 15 RA112 and RC114, a holding circuit for energizing the winding thereof, this circuit extending from the grounded control conductor C154 by way of RA112, RC114, and the winding of R110 to battery. Also, upon operating, the cut-off magnet R110 20 completes, at RA115 and RA116, the holding circuit for energizing the line magnet R120, this circuit extending from ground at the lower winding of R120 by way of the lower winding of R120, RA116, RA115, and the upper winding of R120 to 25 battery. Also, upon operating, the cut-off magnet R110 releases the locking arrangement associated with the armature of the line magnet R120, thereby to allow the line magnet R120 to operate fully. When energized over the above-traced circuit the 30 line magnet R120 fully operates to complete, at RA121 and RC122, a path for applying ground potential to the control conductor C153 of the subscriber line 150 extending to the contact banks 35 of the Strowger mechanisms included in the finder switches of the links having access thereto, thereby to mark the subscriber line 150 as busy, this path extending from the grounded control conductor C154 by way of RC122 and RA121 to the control conductor C153. The subscriber at the 40 substation A then answers the call by removing the receiver of the telephone instrument thereat from its hook, thereby to cause the connector switch 102 to operate in order to interrupt the projection of ringing current over the called subscriber line and to complete an established communication connection between the calling subscriber line 160 and the called subscriber line 150 by way of the operated link 100.

The release of this established connection is 50 under the control of the last party to replace the receiver of the telephone instrument at his station upon its hook, as previously assumed; and the exact manner in which the operated link 100 and the operated line circuits 105 and 104, respectively, 55 individually associated with the subscriber lines 160 and 150 are released is the same as that previously described.

A reverting call which is to be extended from the subscriber substation A to the subscriber substation B is first initiated at the substation A by removing the receiver of the telephone instrument thereat from its hook, thereby to complete the previously traced bridge circuit for energizing in series the windings of the line magnet R120. 65 When thus energized the line magnet R120 partially operates, as previously explained, thereby to close the "X" contacts associated with the switch springs RA121 and RC122, and RA128 and the associated switch spring, in order to cause battery potential to be applied to the control conductor C153 and ground potential to be applied to the start conductor C190, as previously noted. This application of ground potential to the start conductor C190 causes the distributor 103 to oper- 70 75

ate and assign a previously selected idle link in the group of links to the use of the calling subscriber line 150. Assuming that the illustrated link 100 is assigned to the use of the calling subscriber line 150, this application of ground potential to the start conductor C190 and this application of battery potential to the control conductor C153 marks the position of the contact set in the contact bank of the Strowger mechanism included in 10 the finder switch 101 at which the subscriber line 150 is terminated. The finder switch 101 then operates in the previously described manner, thereby to seize the calling subscriber line 150. When the calling subscriber line 150 is seized the 15 cut-off magnet R110 operates to release the latching arrangement associated with the armature of the line magnet R120, and to complete the previously traced holding circuit for energizing in series the upper and lower windings of the line 20 magnet R120 in order to allow the line magnet R120 to operate fully. At this time the line and cut-off magnets R120 and R110 are completely operated, as previously noted.

The connector switch 102 is conditioned to be 25 responsive to a series of dialed digits at this time. The subscriber at the substation A then dials at the dial mechanism thereat successively two predetermined digits into the connector switch 102, thereby to cause the connector switch to operate 30 and select the first trunk line terminating thereat to which an idle reverting call switch is connected. When these two predetermined digits are successively dialed the connector switch 102 operates as 35 a trunk hunting connector switch in order to select a trunk line associated with an idle one of the reverting call switches or to return busy tone current over the loop circuit extending to the calling subscriber substation A in the event that all 40 of the reverting call switches are busy. Assuming that the illustrated reverting call switch 200 is the first idle switch, the connector switch 102 operates to seize the trunk line 170 extending thereto. The reverting call switch 200 is marked as idle or busy, respectively, by the presence of battery or ground 45 potential upon the control conductor C172 of the trunk line 170. At this time, the reverting call switch 200 being idle, battery potential appears upon the control conductor C172 of the trunk line 170, the path for connecting battery potential 50 to the control conductor C172 extending from battery at the resistor 206 by way of the resistor 206, RA271, RC242, RA241, and RA256 to the control conductor C172. When the connector switch 102 selects the trunk line 170 extending to the idle 55 reverting call switch 200, further operation thereof is arrested due to the presence of battery potential upon the control conductor C172 thereof, in the usual manner.

When the trunk line 170 is thus seized by the 60 connector switch 102, this connector switch operates to complete a loop circuit between the calling subscriber substation A and the line relay R230 in the reverting call switch 200, this loop circuit extending from ground at the lower winding of 65 R230 by way of the lower winding of R230, RC229, and RA221 to C173, and from battery at the upper winding of R230 by way of the upper winding of R230, RC222, and RA221 to C171, the line conductors C171 and C173 of the trunk line 170 being 70 connected by way of the operated link 100 to the line conductors C151 and C152, respectively, of the calling subscriber line 150, and the telephone instrument at the substation A being included in a bridge path extending between the line conductors C151 and C152 of the subscriber line 150.

When energized over the above-traced circuit the line relay R230 operates to complete, at RA231 and RC232, an obvious circuit for energizing the hold relay R240. When thus energized the hold relay R240 operates to interrupt, at RA241 and RC242, a point in the path for applying battery potential to the control conductor C172 of the trunk line 170, and completes, at RA241 and RC243, a path for applying ground potential to the control conductor C172, this path extending from ground, at RC243, by way of RA241, and RA256 to the control conductor C172. This application of ground potential to the control conductor C172 of the trunk line 170 marks this trunk line as busy to the connector switches of the links 15 having access thereto, and causes the switch-through relay in the connector switch 102 to operate. When the switch-through relay in the connector switch 102 operates, ground potential in the operated link 100 is removed from the wipers 181 and 184 of the finder and connector switches 101 and 102, respectively, the link 100 and the line circuit 104 being retained in its operated position 20 at this time due to the application of ground potential to the control conductor C172 of the trunk line 170. Also, upon operating, the relay R240 prepares, at RA245, a point in an impulse circuit traced hereinafter for energizing the rotary magnets M236 and M238 of the minor switches 280 and 290, respectively, included in the 25 reverting call switch 200.

The subscriber at the calling substation A then dials at the dial mechanism thereat a third digit corresponding to the last digit of the directory number of the calling substation A, thereby to 30 transmit a series of impulses by way of the previously mentioned loop circuit to the line relay R230. The relay R230 follows the dialed impulses in the usual manner, restoring each time the loop circuit is interrupted and operating each 35 time the loop circuit is completed. Each time the relay R230 restores, it interrupts, at RA231 and RC232, the circuit for energizing the hold relay R240, and completes, at RA231 and RC233, a circuit for energizing in multiple the relay 40 R250 and the rotary magnet M236 of the minor switch 280. The last-mentioned circuit extends from ground, at RA231, by way of RC233, RA245, and RA262 to RC264, one branch of this 45 circuit extending from RC264 by way of the winding of R250 to battery, and the other branch extending from RC264 by way of RA273, RC276, and the winding of M236 to battery. The relays R240 and R250, being of the slow-to-release type, remain operated during impulsing. Each time 50 the circuit for energizing the rotary magnet M236 is completed and interrupted, this magnet operates to drive the wipers 283 and 285 of the rotary switches 281 and 282, respectively, included in the minor switch 280 one step away 55 from their normal positions. When the wipers noted of the rotary switches 281 and 282 are driven away from their normal positions, the switch springs 234 are actuated into engagement, thereby to prepare a circuit traced hereinafter 60 for energizing the transfer relay R270, this circuit being interrupted at this time, at RA251, by the operated relay R250. In response to this 65 digit the wipers 283 and 285 of the rotary switches 281 and 282, respectively, are driven a number 70 of steps away from their normal positions corresponding to this dialed digit and into engagement with corresponding contacts in the associated contact banks 284 and 286, respectively. At the conclusion of the third digit the line re- 75

lay R230 reoperates, thereby to interrupt, at RA231 and RC233, the circuit for energizing in multiple the relay R250 and the rotary magnet M236 in order to cause the relay R250 to restore shortly thereafter and to arrest further operation of the rotary magnet M236. Upon restoring, the relay R250 completes, at RA251, the previously mentioned circuit for energizing the transfer relay R270, this circuit extending from ground, at 10 the switch springs 234, by way of the switch springs 234, RA251, and the winding of R270 to battery. When thus energized the relay R270 operates to complete, at RA272, an obvious holding circuit for energizing the winding thereof, 15 to interrupt, at RA273 and RC276, a further point in the previously traced circuit for energizing the rotary magnet M236, and to prepare, at RA273 and RC274, a point in a circuit traced hereinafter for energizing in multiple the relay 20 R250 and the rotary magnet M238 of the minor switch 290.

The subscriber at the calling substation A then dials at the dial mechanism thereat a fourth digit corresponding to the last digit of the 25 directory number of the called substation B, thereby to transmit another series of impulses by way of the previously mentioned loop circuit to the line relay R230. The relay R230 follows the dialed impulses in the usual manner. Each time the 30 relay R230 restores it interrupts, at RA231 and RC232, the circuit for energizing the hold relay R240, and completes, at RA231 and RC233, the previously mentioned circuit for energizing in multiple the relay R250 and the rotary magnet 35 M238 of the minor switch 290. The last-mentioned circuit extends from ground, at RA231, by way of RC233, RA245, and RA262 to RC264, one branch of this circuit extending from RC264 by way of the winding of R250 to battery, and 40 the other branch extending from RC264 by way of RA273, RC274, and the winding of M238 to battery. Each time the circuit for energizing the rotary magnet M238 is completed and interrupted, this magnet operates to drive the wipers 45 293 and 295 of the rotary switches 291 and 292, respectively, included in the minor switch 290 one step away from their normal positions. When the wipers noted of the rotary switches 291 and 292 are driven away from their normal 50 positions the switch springs 235 are actuated into engagement, thereby to prepare a circuit traced hereinafter for energizing the transfer relay R260, this circuit being interrupted at this time, at RA252, by the operated relay R250. In response to this digit the wipers 293 and 295 of 55 the rotary switches 291 and 292, respectively, are driven a number of steps away from their normal positions corresponding to this dialed digit and into engagement with corresponding contacts in the associated contact banks 294 and 60 296, respectively. At the conclusion of the fourth digit the line relay R230 reoperates, thereby to interrupt, at RA231 and RC233, the circuit for energizing in multiple the relay R250 and the 65 rotary magnet M238 in order to cause the relay R250 to restore shortly thereafter and to arrest further operation of the rotary magnet M238. Upon restoring, the relay R250 completes, at RA252, the previously mentioned circuit for 70 energizing the transfer relay R260, this circuit extending from ground, at the switch springs 235, by way of the switch springs 235, RA252, and the winding of R260 to battery. When thus energized the relay R260 operates to complete, at 75 RA261, an obvious holding circuit for energiz-

ing the winding thereof, to interrupt, at RA262 and RC264, a further point in the previously traced circuit for energizing in multiple the relay R260 and the rotary magnet M238, and to prepare, at RA262 and RC263, a circuit traced hereinafter for energizing the relay R210. 5

Shortly after the conclusion of the fourth digit dialed the subscriber at the substation A replaces the receiver of the telephone instrument thereat upon its hook, thereby to interrupt the 10 loop circuit extending to the line relay R230 in order to cause the latter relay to restore. Upon restoring, the relay R230 completes, at RA231 and RC233, the previously mentioned circuit for energizing the relay R210, this circuit extending 15 from ground, at RA231, by way of RC233, RA245, RA262, RC263, RA258, and the winding of R210 to battery. When thus energized the relay R210 operates to complete, at RA211, an obvious path 20 for applying ground potential to the ringing machine start lead C206, to prepare, at RA212, a holding circuit traced hereinafter for energizing the switch-through relay R220, to complete, at RA213, a path extending from battery, at the winding of R220, by way of the winding of R220, 25 RA225, RC226, and RA213 to the ring pick-up lead C215 for applying battery potential to C215, and to complete, at RA214, an obvious holding circuit for energizing the hold relay R240. The hold relay R240, being of the slow-to-release type, 30 does not restore incident to the restoration of the line relay R230, and is retained in its operated position over the above-mentioned holding circuit for energizing the winding thereof. Accordingly, ground potential is not removed from the 35 control conductor C172 of the trunk line 170 incident to the restoration of the line relay R230.

Shortly thereafter and at the beginning of a code ringing cycle, ground potential is applied in the ringing machine to the ring pick-up lead 40 C215, thereby to complete a circuit for energizing the switch-through relay R220, this circuit extending from the grounded ring pick-up lead C215 by way of RA213, RC226, RA225, and the winding of R220 to battery. When thus energized the relay R220 operates to complete, at RA224 and RA225, a holding circuit for energizing the winding thereof extending from ground, at RA212, by way of RA224, RA225, and the winding of R220 to battery, and to interrupt, at RA225 45 and RC226, the original circuit for energizing the winding thereof by way of the ring pick-up lead C215. Also, the relay R220 interrupts, at RA221 and RC222, and at RA227 and RC229, further points in the loop circuit for energizing the line relay R230, and completes, at RA221 and RC223, and at RA227 and RC228, points in a circuit traced hereinafter for projecting ringing current from the ringing machine associated with the trunk line 206' by way of the operated reverting 50 call switch 200, the trunk line 170, and the link 100 over the subscriber line 150, the exact circuit for projecting ringing current from the ringing machine associated with the trunk line 206' over the subscriber line 150 depending upon the positions of the wipers of the rotary switches included in the minor switches 280 and 290, in a manner more fully described subsequently. 55

As previously noted, a divided ringing circuit is employed in the system, a first group of subscriber substations associated with each party line having ringers thereat connected between one line conductor of the party line and ground, and a second group of subscriber substations associated with each party line having ringers thereat 60 70 75

connected between the other line conductor of the party line and ground. The operation of the reverting call switch 200 depends upon whether the calling and called subscriber substations A and B are in the same group. In the event these subscriber substations are in the same group, the reverting call switch 200 operates to cause ringing current of the code corresponding to the called subscriber substation to be projected over the line conductor of the subscriber line 150, to which the ringers at each of the subscriber substations A and B are connected. In the event these subscriber substations are in different groups, the reverting call switch 200 operates first to cause ringing current of the code corresponding to the called subscriber substation to be projected over the line conductor of the subscriber line 150, to which the ringer at the called substation B is connected, and then to cause ringing current of the code corresponding to the calling subscriber substation to be projected over the line conductor of the subscriber line 150, to which the ringer at the calling substation A is connected. Also, it is noted that the subscriber substations associated with the subscriber line 150 and having ringers connected to one line conductor thereof are assigned directory numbers comprising a third odd digit, and the subscriber substations associated with the subscriber line 150 and having ringers connected to the other line conductor thereof are assigned directory numbers comprising a third even digit.

Assuming that the third digit of the directory number of the calling subscriber substation A is the No. 1, and the third digit of the directory number of the called subscriber substation B is the No. 3, the wipers of the rotary switches of the minor switch 280 engage the first contacts in the associated contact banks, and the wipers of the rotary switches of the minor switch 290 engage the third contacts in the associated contact banks. At this time a circuit is completed for projecting ringing current of the code corresponding to the called subscriber substation B over the subscriber line 150, this circuit extending from the ungrounded terminal of the ringing machine winding by way of the ringing conductor M3, the third contact in the contact bank 294 and the associated wiper 293 of the rotary switch 291, the upper winding of the ring cut-off relay R255, RC223, and RA221, to the line conductor C171 of the trunk line 170, and therefrom by way of the operated link 100, the line conductor C151 of the subscriber line 150, and a condenser and the ringer at the called substation B, to ground. Also, a circuit is prepared for energizing the upper winding of the ring cut-off relay R255, which is completed when the subscriber at the substation B answers the call by removing the receiver of the telephone instrument thereat from its hook, this circuit extending, when completed, by way of the previously traced path to the line conductor C151 of the subscriber line 150, and therefrom by way of the bridge path at the substation B between the line conductors C151 and C152 of the subscriber line 150, C152, the operated link 100, the line conductor C173 of the trunk line 170, RA221, RC228, and the windings 202 and 203 of the transformer 201 to ground.

Assuming that the third digit of the directory number of the calling subscriber substation A is the No. 2, and the third digit of the directory number of the called subscriber substation B is the No. 4, the wipers of the rotary switches of the minor switch 280 engage the second con-

tacts in the associated contact banks, and the wipers of the rotary switches of the minor switch 290 engage the fourth contacts in the associated contact banks. At this time a circuit is completed for projecting ringing current of the code corresponding to the called subscriber substation B over the subscriber line 150, this circuit extending from the ungrounded terminal of the ringing machine winding by way of the ringing conductor M4, the fourth contact in the contact bank 296 and the associated wiper 295 of the rotary switch 292, and the windings 205 and 204 of the transformer 201 to ground at RA220. This ringing current traversing the windings 204 and 205 of the transformer 201 induces a corresponding ringing current in the windings 202 and 203 thereof, which traverses a path extending from ground by way of the windings 203 and 202, RC228, RA227, to the line conductor C173 of the trunk line 170, and therefrom by way of the operated link 100, the line conductor C152 of the subscriber line 150, and the condenser and the ringer at the called substation B to ground. Also, a circuit is prepared for energizing the upper winding of the cut-off relay R255, which is completed when the subscriber at the substation B answers the call by removing the receiver of the telephone instrument thereat from its hook, this circuit extending, when completed, from battery at the resistor 207, by way of the resistor 207, the second contact in the contact bank 284 and the associated wiper 283 of the rotary switch 281, the fourth contact in the contact bank 294 and the associated wiper 293 of the rotary switch 291, the upper winding of R255, RC223, RA221, the line conductor C171 of the trunk line 170, and the operated link 100 to the line conductor C151, and therefrom by way of the bridge path at the substation B between the line conductors C151 and C152 of the subscriber line 150, and a portion of the previously traced circuit to ground, at the winding 203 of the transformer 201.

Assuming that the third digit of the directory number of the calling subscriber substation A is the No. 1, and the third digit of the directory number of the called subscriber substation B is the No. 2, the wipers of the rotary switches of the minor switch 280 engage the first contacts in the associated contact banks, and the wipers of the rotary switches of the minor switch 290 engage the second contacts in the associated contact banks. At this time a circuit is completed for projecting ringing current of the code corresponding to the called subscriber substation B over the subscriber line 150, this circuit extending from the ungrounded terminal of the ringing machine winding by way of the ringing conductor M2, the second contact in the contact bank 296 and the associated wiper 295 of the rotary switch 292, and the windings 205 and 204 of the transformer 201 to ground at RA220. This ringing current traversing the windings 204 and 205 of the transformer 201 induces a corresponding ringing current in the windings 202 and 203 thereof which is projected by way of the previously traced path over the line conductor C152 of the subscriber line 150 to ground at the ringer at the called substation B. Also a circuit is completed for projecting ringing current of the code corresponding to the calling subscriber substation A over the subscriber line 150, this circuit extending from the ungrounded terminal of the ringing machine winding by way of the ringing conductor M1, the first contact in the contact bank 284 and the associated wiper 283 of the rotary switch 281,

the second contact in the contact bank 294 and the associated wiper 293 of the rotary switch 291, the upper winding of the ring cut-off relay R255, RC223, RA221, the line conductor C171 of the 5 trunk line 170, the operated link 100, the line conductor C151 of the subscriber line 150, and a condenser and the ringer at the calling substation A to ground. The ringing machine operates to complete the circuits for applying ringing 10 currents to the ringing conductors M1 to M5, inclusive, sequentially, thereby to cause the ringer at the called substation B and the ringer at the calling substation A to be operated alternatively. Also a circuit is prepared for energizing the upper 15 winding of the ring cut-off relay R255, which is completed when the subscriber at the substation B answers the call by removing the receiver of the telephone instrument thereat from its hook, this circuit extending, when completed, from the 20 ringing conductor M1 by way of the previously traced path to ground at the winding 203 of the transformer 201.

Assuming that the third digit of the directory number of the calling subscriber substation A is the No. 2, and the third digit of the directory number of the called subscriber substation B is the No. 1, the wipers of the rotary switches of the minor switch 280 engage the second contacts in the associated contact banks, and the wipers 30 of the rotary switches of the minor switch 290 engage the first contacts in the associated contact banks. At this time a circuit is completed for projecting ringing current of the code corresponding to the calling subscriber substation 35 B over the subscriber line 150, this circuit extending from the ungrounded terminal of the ringing machine winding by way of the ringing conductor M1, the first contact in the contact bank 294 and the associated wiper 293 of the 40 rotary switch 291, the upper winding of R255 and a portion of the previously traced circuit including the line conductor C151 of the subscriber line 150 to ground at the ringer at the called substation B. Also a circuit is completed for projecting ringing current of the code corresponding 45 to the calling substation A over the subscriber line 150, this circuit extending from the ungrounded terminal of the ringing machine winding by way of the ringing conductor M2, the second contact in the contact bank 286 and the associated wiper 285 of the rotary switch 282, the 50 first contact in the contact bank 296 and the associated wiper 295 of the rotary switch 292, and the windings 205 and 204 of the transformer 55 201 to ground, at RA220. This ringing current traversing the windings 204 and 205 of the transformer 201 induces a corresponding ringing current in the windings 202 and 203 thereof which is projected by way of the previously traced circuit 60 including the line conductor C152 of the subscriber line 150 to ground at the ringer at the calling substation A. As previously noted, the ringers at the called and calling subscriber substation B and A, respectively, are operated alternatively. Also a circuit is prepared for energizing the upper winding of the ring cut-off relay R255, which is completed when the subscriber at the substation B answers the call by 65 removing the receiver of the telephone instrument thereat from its hook, this circuit extending, when completed, from the ringing conductor M1 by way of the previously traced path to ground at the winding 203 of the transformer 201.

When the subscriber at the called substation B 70 answers the call, one of the previously traced cir-

cuits for energizing the upper winding of the ring cut-off relay R255 is completed, depending upon whether the calling and called substations A and B, respectively, are in the same or different groups, as previously noted. When thus energized the ring cut-off relay R255 operates to complete, at RA257, a holding circuit for energizing the lower winding thereof, this circuit extending from ground, at RA244, by way of RA257 and the lower winding of R255 to battery. Also 10 the relay R255 interrupts, at RA256, the previously traced path for applying ground potential to the control conductor C172 of the trunk line 170, and interrupts, at RA258, the circuit for energizing the relay R210, thereby to cause the latter relay to restore. Upon restoring, the relay R210 interrupts, at RA211, the previously traced path for applying ground potential to the ringing machine start lead C206 in order to arrest further 15 operation of the ringing machine associated with the reverting call switch 200, to interrupt, at RA212, the holding circuit for energizing the relay R220 in order to cause the latter relay to restore, and to interrupt, at RA214, the previously 20 traced holding circuit for energizing the hold relay R240. Shortly thereafter the hold relay R240 restores to interrupt, at RA244, the holding circuit for energizing the lower winding of the ring cut-off relay R255 in order to cause the latter relay to restore shortly thereafter, and to complete, at RA246, a circuit for energizing the release magnet M239 of the minor switch 290, this 25 circuit extending from ground, at RA246, by way of RA265, RC266, and the winding of M239 to battery. When thus energized the release magnet M239 operates to release the wipers of the rotary switches 291 and 292 of the minor switch 290, thereby to cause these wipers to be returned to their normal positions. When the wipers 30 noted of the rotary switches of the minor switch 290 are returned to their normal positions, the switch springs 235 are actuated into disengagement, thereby to interrupt the holding circuit for energizing the transfer relay R260. The transfer relay R260 then restores to interrupt, at RA265 and RC266, the circuit for energizing the release magnet M239, and to complete, at RA265 and RC267, a circuit for energizing the release magnet M237 of the minor switch 280, this circuit extending from ground, at RA246, by 35 way of RA265, RC267, RA271, and the winding of R237 to battery. When thus energized the release magnet M237 operates to release the wipers of the rotary switches 281 and 282 of the minor switch 280, thereby to cause these wipers to be returned to their normal positions. When the wipers 40 noted of the rotary switches of the minor switch 280 are returned to their normal positions, the switch springs 234 are actuated into disengagement, thereby to interrupt the holding circuit for energizing the transfer relay R270. The transfer relay R270 then restores to interrupt, at RA271, the circuit for energizing the release magnet M237. Upon restoring, the hold relay R240, the ring cut-off relay R255, and the transfer relay R270 complete, at RA241 and RC242, at RA256 and at RA271, respectively, the 45 previously traced path for connecting battery at the resistor 206 to the control conductor C172 of the trunk line 170, thereby to mark this trunk line as idle to the connector switches of the links having access thereto. At this time the reverting call switch 200 is completely released for further use.

call switch 200 operates when the call is answered at the called subscriber substation B to interrupt, at RA256, the path for applying ground potential to the control conductor C172 of the 5 trunk line 170, thereby to cause the link 100 to be released and interrupt the holding circuit for energizing the winding of the cut-off magnet R110 in the line circuit 104 individually associated with the subscriber line 150. The cut-off 10 magnet R110 then restores to complete, at RA116 and RC117, and at RA111, a bridge circuit for energizing the windings of the line magnet R120, thereby to retain this line magnet in its fully 15 operated position. This circuit extends from ground, at the lower winding of R120, by way of the lower winding of R120, RA116, RC117, C152, the bridge path including the telephone instrument at the called subscriber substation B between the line conductors C152 and C151 of 20 the subscriber line 150, C151, RA111, and the upper winding of R120 to battery. Also, upon restoring, the cut-off magnet R110 interrupts, at RA115 and RA116, the previously traced holding circuit for energizing in series the upper and 25 lower windings of the line magnet R120, interrupts, at RA112 and RC114, a further point in the holding circuit for energizing the winding of R110, and completes, at RA112 and RC113, a path for applying ground potential to the control 30 conductors C153 and C154 of the subscriber line 150, this path extending from ground, at RA126, by way of RA125 and RC113 to RA112, one branch of this path extending from RA112 to C154, and the other branch extending from 35 RA112, by way of RC122 and RA121, to C153. This application of ground potential to the control conductor C154, extending to the contact banks of the Strowger mechanisms included in the connector switches of the links having access 40 to the subscriber line 150, marks the subscriber line as busy thereto. Also, this application of ground potential to the control conductor C153, extending to the contact banks of the Strowger mechanisms included in the finder switches of 45 the links having access to the subscriber line 150, marks this subscriber line as busy thereto. Due to the fact that the bridge circuit for energizing the windings of the line magnet R120 is completed prior to the interruption of the holding 50 circuit for energizing the windings thereof, as previously noted, the line magnet R120 remains in its fully operated position. At this time the line circuit 104 is operated to lock the subscriber line 150 out of service; and talking battery is 55 supplied by way of the previously traced bridge circuit to the telephone instrument at the called subscriber substation B.

As previously noted, when the subscriber at the called substation B answers the call the reverting call switch 200 is released, thereby to interrupt the circuit for projecting ringing current over the subscriber line 150 in order to cause further operation of the ringer at the calling subscriber substation A to be arrested. When 60 the operation of the ringer at the calling subscriber substation A is arrested, the subscriber thereat is advised that the subscriber at the called substation B has answered the call. The subscriber at the substation A then removes the receiver of the telephone instrument thereat from its hook, thereby to complete an established connection between the calling and called subscriber substations A and B, respectively, for two-way communication therebetween, talking bat- 65

tery being supplied to the substation A by way of the previously traced bridge circuit.

The release of this established connection between the subscriber substations A and B is under the control of the last subscriber to replace the receiver of the telephone instrument at his substation upon its hook. When the last subscriber replaces the receiver of the telephone instrument at his substation upon its hook, the bridge circuit for energizing the windings of the line magnet R120 is interrupted, thereby to cause this line magnet to restore completely, as previously noted. At this time the established connection between the subscriber substations A and B is completely released, and the line circuit 104 15 individually associated with the subscriber line 150 is released, thereby to mark this subscriber line as idle to the finder and connector switches of the links having access thereto.

A reverting call which is to be extended from the subscriber substation C to the subscriber substation D is first initiated at the substation C by removing the receiver of the telephone instrument thereat from its hook, thereby to complete the previously traced bridge circuit for energizing in series the windings of the line magnet R130. When thus energized the line magnet R130 partially operates, as previously explained, thereby to close the "X" contacts associated with the switch springs RA131, RC132, and RA133, RC134, and RA137 and the associated switch spring, and to open the "X" contact associated with the switch springs RA133, RC133, in order to cause battery potential to be applied to the control conductor C164, ground potential to be applied to the control conductor C163, and ground potential to be applied to the start conductor C190, as previously noted. This application of ground potential to the start conductor C190 causes the distributor 103 to operate 40 and assign a previously selected idle link in the group of links to the use of the calling subscriber line 160. Assuming that the illustrated link 100 is assigned to the use of the calling subscriber line 160, this application of ground potential to 45 the start conductor C190, and this application of battery potential to the control conductor C164, marks the position of the contact set in the contact bank of the Strowger mechanism included in the finder switch 101 at which the subscriber line 160 is terminated. The finder switch 101 then operates in the previously described manner, thereby to seize the calling subscriber line 160. When the calling subscriber line 160 is seized, the cut-off magnet R140 operates to release the latching arrangement associated with the armature of the line magnet R130, and to complete the previously traced holding circuit for energizing in series the upper and lower windings of the line magnet R130 in order to allow the line magnet R130 to operate fully. At this time the line and cut-off magnets R130 and R140 are completely operated, as previously noted.

The connector switch 102 is conditioned to be 65 responsive to a series of dialed digits at this time. The subscriber at the substation C then dials at the dial mechanism thereat successively two predetermined digits into the connector switch 102, thereby to cause this connector switch to 70 operate as a trunk hunting connector switch and seize an idle line in the group of trunk lines extending to reverting call switches in the event there is an idle reverting call switch in this group, or to return busy tone current over the loop cir- 75

cuit extending to the calling subscriber substation C in the event all of the reverting call switches in this group are busy. Assuming that the reverting call switch 200 is the first idle switch in this group, the connector switch 102 operates to seize the trunk line 170 extending thereto, this trunk line being marked as idle by the presence of battery potential upon the control conductor C172, in the previously described manner. When the trunk line 170 is seized by the connector switch 102, further operation of this connector switch is arrested, and the reverting call switch 200 is conditioned to be responsive to two series of successively dialed digits. Also the reverting call switch 200 operates to apply ground potential to the control conductor C172 of the trunk line 170, thereby to cause the switch-through relay in the connector switch 102 to operate. When the switch-through relay in the connector switch 102 operates, a loop circuit is completed between the calling subscriber substation C and the reverting call switch 200, and ground potential is removed in the operated link 100 from the wipers 181 and 184 of the finder 25 and connector switches 101 and 102, respectively, the link 100 and the line circuit 105 individually associated with the subscriber line 160 being retained in their operated positions at this time due to the presence of ground potential upon the control conductor C172 of the trunk line 170. The subscriber at the calling substation C then dials successively two digits at the dial mechanism thereat into the reverting call switch 200, the third digit dialed corresponding to the third digit 30 of the directory number of the calling subscriber substation C, and the fourth digit corresponding to the third digit of the directory number of the called subscriber substation D. The subscriber at the calling substation C then replaces 35 the receiver of the telephone instrument thereat upon its hook, and the reverting call switch 200 then operates, as previously described, thereby to project ringing current over the line conductor of the subscriber line 160 to which the ringers at 40 the calling and called subscriber substations C and D, respectively, are connected in the event the ringers at both of these subscriber substations are included in the same group, and to project alternately ringing current over the line conductors of the subscriber line 160 in the event that the calling and called subscriber substations C and D, respectively, are included in different groups, 45 as previously noted. This ringing current projected over the subscriber line 160 causes the ringer at the called subscriber substation D to operate in a characteristic manner, thereby to indicate to the subscriber thereat that the substation D is the called substation.

The subscriber at the called substation D then 50 answers the call by removing the receiver of the telephone instrument thereat from its hook, thereby to complete a loop circuit for energizing the upper winding of the ring cut-off relay R255 in the reverting call switch 200 and extending between the substation D and reverting call switch 55 200. When thus energized, the ring cut-off relay R255 operates, in the previously described manner, thereby to interrupt, at RA256, the path for applying ground potential to the control conductor C172 of the trunk line 170, and to cause the reverting call switch 200 to be released.

When the path for applying ground potential to the control conductor C172 of the trunk line 170 is interrupted, the operated link 100 is released for further use, and the holding circuit

for energizing the cut-off magnet R140 in the line circuit 105 individually associated with the subscriber line 160 is interrupted, thereby to cause the latter magnet to restore. Upon restoring, the cut-off magnet R140 completes, at RA146 and RC148, and at RA141, a bridge circuit for energizing the windings of the line magnet R130, this circuit extending from ground, at the lower winding of R130, by way of the lower winding of R130, RA146, RC148, C162, the bridge path at the telephone instrument at the called substation D between the line conductors C162 and C161 of the subscriber line 160, C161, RA141, and the upper winding of R130 to battery. Also the cut-off magnet R140 interrupts, at RA146 and RA147, 10 the previously traced holding circuit for energizing in series the upper and lower windings of the line magnet R130 subsequent to the completion of the above-traced bridge circuit for energizing these windings of the line magnet R130. Thus the line magnet R130 remains in its fully operated position. Further, the cut-off magnet R140 interrupts, at RA144 and RC145, a further point in the holding circuit for energizing the winding thereof, and interrupts, at RA142 and RC143, the connection between the control conductor C163 and the control conductor C164 of the subscriber line 160. Further, the cut-off magnet R140 completes, at RA149, a path for applying ground potential to the control conductor C163, extending to the contact banks of the Strowger mechanisms included in the connector switches of the links having access thereto, thereby to mark the subscriber line 160 as busy thereto, this path extending from ground, at RA149, by way of RA139, to the control conductor C163. Finally, the cut-off magnet R140 completes, at RA140', a path for applying ground potential to the control conductor C164 of the subscriber line 160 extending to the contact banks of the Strowger mechanisms included in the finder switches of the links having access thereto, thereby to mark the subscriber line 160 as busy thereto, this path extending from ground, at RA130, by way of RA140' to the control conductor C164. 40 At this time talking battery is supplied to the telephone instrument at the substation D by way of the bridge circuit for energizing the windings of the line magnet R130, and the line circuit 105 individually associated with the subscriber line 160 is operated to lock this subscriber line out of service.

As previously noted, when the subscriber at the called substation D answers the call, the reverting call switch 200 is released, thereby to 55 interrupt the circuit for projecting ringing current over the subscriber line 160 in order to cause further operation of the ringer at the calling subscriber substation C to be arrested. When the operation of the ringer at the calling subscriber substation C is arrested, the subscriber thereat is advised that the subscriber at the called substation D has answered the call. The subscriber at the substation C then removes the receiver of the telephone instrument thereat from its hook, 60 thereby to complete an established connection between the calling and called subscriber substations C and D, respectively, for two-way communication therebetween, talking battery being supplied to the substation C by way of the previously traced bridge circuit.

The release of this established connection between the subscriber substations C and D is under the control of the last subscriber to replace the receiver of the telephone instrument at his sub- 75

station upon its hook. When the last subscriber replaces the receiver of the telephone instrument at his substation upon its hook, the bridge circuit for energizing the windings of the line magnet R130 is interrupted, thereby to cause this line magnet to restore completely, as previously noted. At this time the established connection between the subscriber substations C and D is completely released, and the line circuit 105 individually associated with the subscriber line 160 is released, thereby to mark this subscriber line as idle to the finder and connector switches of the links having access thereto.

Also it is noted that a timing arrangement is incorporated in the connector switch 102 which is operative in the event the switch-through relay therein does not operate within a predetermined time interval, due to the fact that the connector switch has not been fully operated to seize a line accessible thereto, to cause ground potential to be removed from the wiper 181. For example, the link 100 may be seized in the previously described manner by the appearance of a fault on one of the subscriber lines, in which case the connector switch 102 thereof would not be operated subsequently to seize a line accessible thereto in order to cause the operation of the switch-through relay therein, whereby ground potential would be removed from the wiper 181, as previously noted. Under these conditions where ground potential is removed from the wiper 181, the holding circuit for energizing the cut-off magnet in the line circuit associated with the line having the fault thereon is interrupted, thereby to cause the cut-off magnet to restore. In the event the line having a fault thereon has a line circuit of the connection and arrangement of that of the line circuit 104, the cut-off magnet therein, corresponding to the cut-off magnet R110, restores to cause the line to be locked out of service in the manner previously described in connection with the extension of a reverting call between the subscriber substations A and B. In the event the line having a fault thereon has a line circuit of the connection and arrangement of that of the line circuit 105, the cut-off magnet therein, corresponding to the cut-off magnet R140, restores to cause the line to be locked out of service in the manner previously described in connection with the extension of a reverting call between the subscriber substations C and D.

While there have been described what are at present considered to be the preferred embodiments of the invention, it will be understood that various modifications may be made therein, and it is intended to cover in the appended claims all such modifications as fall within the true spirit and scope of the invention.

60. What is claimed is:

1. A line circuit adapted for use in a telephone system including a line accessible to an automatic switch, said line circuit comprising, in combination, line and cut-off relays, said line relay having a restored position and first and second operated positions, means responsive to the creation of a calling condition on said line for causing said line relay to be operated from its restored position to its first operated position, means responsive to the seizure of said line by said automatic switch for causing said cut-off relay to be operated, means controlled by the operation of said cut-off relay for causing said line relay to be operated to its second operated position, and circuits for controlling said automatic switch

governed in accordance with the positions of said line and cut-off relays.

2. A line circuit adapted for use in a telephone system including a line accessible to an automatic switch, said line circuit comprising, in combination, line and cut-off relays, said line relay having a restored position and first and second operated positions, said line relay being operative from its restored position to its first operated position in response to the creation of a calling condition on said line, means effective to prevent operation of said line relay to its second operated position, said cut-off relay being operative in response to the seizure of said line by said automatic switch, means controlled by the operation of said cut-off relay for rendering said last-mentioned means ineffective, whereby said line relay is operated to its second operated position, and circuits for controlling said automatic switch governed in accordance with the positions of said line and cut-off relays.

3. A line circuit adapted for use in a telephone system including a line accessible to an automatic switch, said line circuit comprising, in combination, line and cut-off relays, said line relay having a restored position and first and second operated positions, said line relay being operative from its restored position to its first operated position in response to the creation of a calling condition on said line, mechanical means effective to prevent operation of said line relay to its second operated position, said cut-off relay being operative in response to the seizure of said line by said automatic switch, means controlled by the operation of said cut-off relay for actuating said mechanical means, whereby said line relay is operated to its second operated position, and circuits for controlling said automatic switch in accordance with the positions of said line and cut-off relays.

4. A line circuit adapted for use in a telephone system including a line provided with at least one line conductor and accessible to an automatic switch, said line circuit comprising, in combination, line and cut-off relays, said line relay having a restored position and first and second operated positions, a first circuit including said line conductor for said line relay, a holding circuit for said line relay, said first circuit being completed in response to the creation of a calling condition on said line, whereby said line relay is operated from its restored position to its first operated position, said cut-off relay being operative in response to the seizure of said line by said automatic switch, means controlled by the operation of said cut-off relay for completing said holding circuit and for interrupting said first circuit, whereby said line relay is operated from its first operated position to its second operated position, and circuits for controlling said automatic switch governed in accordance with the positions of said line and cut-off relays.

5. A line circuit adapted for use in a telephone system including a line provided with at least one line conductor and accessible to an automatic switch, said line circuit comprising, in combination, line and cut-off relays, said line relay having a restored position and first and second operated positions, a first circuit including said line conductor for said line relay, a holding circuit for said line relay, said first circuit being completed in response to the creation of a calling condition on said line, whereby said line relay is operated from its restored position to its first operated position, mechanical means effective to

prevent operation of said line relay to its second operated position, said cut-off relay being operative in response to the seizure of said line by said automatic switch, means controlled by the 5 operation of said cut-off relay for actuating said mechanical means, means controlled by the operation of said cut-off relay for completing said holding circuit and for interrupting said first circuit, whereby said line relay is operated from 10 its first operated position to its second operated position, and circuits for controlling said automatic switch governed in accordance with the positions of said line and cut-off relays.

6. A line circuit adapted for use in a telephone 15 system including a line having a plurality of subscriber substations associated therewith and accessible to a number of automatic switches; said line circuit comprising a circuit network consisting solely of line and cut-off relays and automatic switch control and line marking circuits governed by said line and cut-off relays, said circuit network being so connected and arranged that said automatic switches are controlled to render by way of said line calling, called and reverting call services to said substations, and that 25 said line is marked as busy to the remainder of said automatic switches not employed in rendering a service by way of said line while a service is being rendered by way of said line.

7. A line circuit adapted for use in a telephone 30 system including a line having a plurality of subscriber substations associated therewith and accessible to a number of automatic switches; said line circuit comprising a circuit network 35 consisting solely of line and cut-off relays and automatic switch control and line marking circuits governed by said line and cut-off relays; said circuit network being so connected and arranged that said automatic switches are controlled to set up by way of said line outgoing call 40 connections from said substations, incoming call connections to said substations and reverting call connections between two of said substations, and that said line is marked as busy to the remainder of said automatic switches not employed in a connection including said line while a connection 45 including said line is set up.

8. A line circuit adapted for use in a telephone 50 system including a line having a plurality of subscriber substations associated therewith and accessible to a number of automatic switches; said line circuit comprising a circuit network consisting solely of line and cut-off relays and automatic switch control and line marking circuits 55 governed by said line and cut-off relays; said circuit network being so connected and arranged that said automatic switches are controlled to set up by way of said line outgoing call connections from said substations, incoming call 60 connections to said substations and reverting call connections between two of said substations, and that said line is marked as busy to the remainder of said automatic switches not employed in a connection including said line while a connection 65 including said line is set up, and that said line is marked as busy to said automatic switches in the event a fault appears thereon.

9. In a telephone system, a line, a number of 70 finderswitches and a number of connector switches having access to said line, a line circuit associated with said line and including line and cut-off relays, said line relay having a restored position and first and second operated positions, means responsive to the creation of a calling 75 condition on said line for causing said line relay

to be operated from its restored position to its first operated position, means controlled by the operation of said line relay to its first operated position for causing an idle one of said finder switches to seize said line, means responsive to the seizure of said line by said one finder switch for causing said cut-off relay to be operated, means controlled by the operation of said cut-off relay for causing said line relay to be operated from its first operated position to its second operated position, and circuits for controlling said connector switches governed in accordance with the positions of said line and cut-off relays. 5 10

10. In a telephone system, a line, a number of finder switches having access to said line, a line 15 circuit associated with said line and including line and cut-off relays, a distributor associated with said finder switches and operative to cause an idle one of said finder switches to operate and seize a line marked as a calling line, said line relay having a restored position and first and second operated positions, means responsive to the creation of a calling condition on said line for causing said line relay to be operated from its restored position to its first operated position, 20 means controlled by the operation of said line relay to its first operated position for initiating operation of said distributor and for marking said line as a calling line, means responsive to the seizure of said line by one of said finder 25 switches for causing said cut-off relay to be operated, means controlled by the operation of said cut-off relay for causing said line relay to be operated from its first operated position to its second operated position, and means controlled by 30 the operation of said line relay to its second operated position for arresting the operation of said distributor.

11. In a telephone system, a line, a number of finder switches having access to said line, a line 40 circuit associated with said line and including line and cut-off relays, a distributor associated with said finder switches and operative to cause an idle one of said finder switches to operate and seize a line marked as a calling line, said line 45 relay having a restored position and first and second operated positions, means responsive to the creation of a calling condition on said line for causing said line relay to be operated from its restored position to its first operated position, mechanical means effective to prevent operation of said line relay to its second operated position, means controlled by the operation of said line relay to its first operated position for initiating operation of said distributor and for marking said line as a calling line, means responsive to the seizure of said line by one of said finder 50 switches for causing said cut-off relay to be operated, means controlled by the operation of said cut-off relay for actuating said mechanical 55 means and for causing said line relay to be operated from its first operated position to its second operated position, and means controlled by the operation of said line relay to its second operated position for arresting the operation of 60 said distributor.

12. In a telephone system, a line provided with at least one line conductor, a number of finder switches having access to said line, a line circuit associated with said line and including line and cut-off relays, a distributor associated with said finder switches and operative to cause an idle one of said finder switches to operate and seize a line marked as a calling line, said line relay having a restored position and first and 75

second operated positions, a first circuit including said line conductor for said line relay, a holding circuit for said line relay, means responsive to the creation of a calling condition on said line 5 for causing said first circuit to be completed, whereby said line relay is operated from its restored position to its first operated position, mechanical means effective to prevent operation of said line relay to its second operated position, means controlled by the operation of said line relay to its first operated position for initiating operation of said distributor and for marking said line as a calling line, means responsive to the seizure of said line by one of said finder 10 switches for causing said cut-off relay to be operated, means controlled by the operation of said cut-off relay for actuating said mechanical means, means controlled by the operation of said cut-off relay for completing said holding circuit 15 and for interrupting said first circuit, whereby said line relay is operated from its first operated position to its second operated position, and means controlled by the operation of said line relay to its second operated position for arresting 20 the operation of said distributor.

13. A line circuit adapted for use in a telephone system including a line accessible to a number of automatic switches, said line circuit comprising, in combination, line and cut-off relays, said line relay having first and second operated positions, means responsive to the creation of a calling condition on said line for causing said line relay to be operated to said first position, means responsive to the seizure of said line by one of said automatic switches for causing said cut-off relay to be operated, means controlled by the operation of said cut-off relay for causing said line relay to be operated to said second position, means for releasing said one automatic switch, means responsive to the release of said one automatic switch for causing said cut-off relay to be restored, means for causing said line relay to remain operated to said second position subsequent to the restoration of said cut-off relay in the event a calling condition remains on said line, and means controlled when said line relay is operated to said second position and said cut-off relay is restored for marking said line as busy to said automatic switches. 35

14. A line circuit adapted for use in a telephone system including a line accessible to a number of automatic switches, said line circuit comprising, in combination, line and cut-off relays, said line relay having first and second operated positions, said line relay being operative to said first position in response to the creation of a calling condition on said line, mechanical means effective to prevent operation of said line relay to said second position, said cut-off relay being operative in response to the seizure of said line by one of said automatic switches, means controlled by the operation of said cut-off relay for actuating said mechanical means, whereby said line relay is operated to said second position, means for releasing said one automatic switch, said cut-off relay being restored in response to the release of said one automatic switch, said line relay remaining operated to said second position subsequent to the restoration of said cut-off relay in the event a calling condition remains on said line, and means controlled when said line relay is operated to said second position and said cut-off relay is restored for marking said line as busy to said automatic switches. 50

15. A line circuit adapted for use in a tele-

phone system including a line provided with at least one line conductor and accessible to a number of automatic switches, said line circuit comprising, in combination, line and cut-off relays, said line relay having first and second operated positions, a first circuit including said line conductor for said line relay, a holding circuit for said line relay, said first circuit being completed in response to the creation of a calling condition on said line, whereby said line relay is operated to said first position, said cut-off relay being operative in response to the seizure of said line by one of said automatic switches, means controlled by the operation of said cut-off relay for completing said holding circuit and for interrupting said first circuit, whereby said line relay is operated to said second position, means for releasing said one automatic switch, said cut-off relay being restored in response to the release of said one automatic switch, means controlled by the restoration of said cut-off relay for completing said first circuit and for interrupting said holding circuit, whereby said line relay remains operated to said second position in the event a calling condition remains on said line, and means controlled when said line relay is operated to said second position and said cut-off relay is restored for marking said line as busy to said automatic switches. 5

16. In a telephone system, a line, a number of automatic switches having access to said line, a line circuit associated with said line and including line and cut-off relays, said line relay having first and second operated positions, means responsive to the creation of a calling condition on said line for causing said line relay to be operated to said first position, means controlled by the operation of said line relay to said first position for causing an idle one of said automatic switches to seize said line, means responsive to the seizure of said line by said one automatic switch for causing said cut-off relay to be operated, means controlled by the operation of said cut-off relay for causing said line relay to be operated to said second position, means for releasing said one automatic switch, means responsive to the release of said one automatic switch for causing said cut-off relay to be restored, means for causing said line relay to remain operated to said second position subsequent to the restoration of said cut-off relay in the event a calling condition remains on said line, and means controlled when said line relay is operated to said second position and said cut-off relay is restored for marking said line as busy to said automatic switches. 30

17. In a telephone system, a line, a number of finder and connector switches having access to said line, a line circuit associated with said line and including line and cut-off relays, a distributor associated with said finder switches and operative to cause an idle one of said finder switches to operate and seize a line marked as a calling line, said line relay having first and second operated positions, means responsive to the creation of a calling condition on said line for causing said line relay to be operated to said first position, means controlled by the operation of said line relay to said first position for initiating operation of said distributor and for marking said line as a calling line, means responsive to the seizure of said line by one of said finder switches for causing said cut-off relay to be operated, means controlled by the operation of said cut-off relay for causing said line relay to 40

be operated to said second position, means controlled by the operation of said line relay to said second position for arresting the operation of said distributor, means for releasing said one finder switch, means responsive to the release of said one finder switch for causing said cut-off relay to be restored, means for causing said line relay to remain operated to said second position subsequent to the restoration of said cut-off relay in the event a calling condition remains on said line, and means controlled when said line relay is operated to said second position and said cut-off relay is restored for marking said line as busy to said finder and connector switches.

15 18. In a telephone system, a line, a number
of finder and connector switches having access
to said line, a line circuit associated with said
line and including line and cut-off relays, a dis-
tributor associated with said finder switches and
20 operative to cause an idle one of said finder
switches to operate and seize a line marked as a
calling line, said line relay having first and sec-
ond operated positions, means responsive to the
creation of a calling condition on said line for
25 causing said line relay to be operated to said
first position, mechanical means effective to pre-
vent operation of said line relay to said second
position, means controlled by the operation of
30 said line relay to said first position for initiating
operation of said distributor and for marking
said line as a calling line, means responsive to the
seizure of said line by one of said finder switches
35 for causing said cut-off relay to be operated,
means controlled by the operation of said cut-
off relay for actuating said mechanical means and
for causing said line relay to be operated to said
second position, means controlled by the opera-
40 tion of said line relay to said second position for
arresting the operation of said distributor, means
45 for releasing said one finder switch, means re-
sponsive to the release of said one finder switch
for causing said cut-off relay to be restored,
means for causing said line relay to remain oper-
ated to said second position subsequent to the
50 restoration of said cut-off relay in the event a
calling condition remains on said line, and means
controlled when said line relay is operated to
said second position and said cut-off relay is re-
stored for marking said line as busy to said
finder and connector switches.

19. In a telephone system, a line, a plurality of subscriber substations associated with said line, a number of automatic switches having access to said line, a line circuit associated with said line and including line and cut-off relays, said line relay having first and second operated positions, means responsive to the initiation of a call at a calling one of said substations for creating a calling condition on said line, means responsive to the creation of a calling condition on said line for causing said line relay to be operated to said first position, means controlled by the operation of said line relay to said first position for causing an idle one of said automatic switches to seize said line, means responsive to the seizure of said line by said one automatic switch for causing said cut-off relay to be operated, means controlled by the operation of said cut-off relay for causing said line relay to be operated to said second position, impulse responsive means operative to cause ringing current to be projected by way of said one automatic switch over said line subsequent to the termination of the calling condition thereon and to cause said cut-off relay to remain operated, means responsive to the projection of said ringing current for causing said line relay to be operated to said second position, and means for causing the projection of said ringing current to be terminated.

sive to the answering of the call at a called one of said substations for causing said one automatic switch to be released and for creating a new calling condition on said line, means responsive to the release of said one automatic switch for causing said cut-off relay to be restored, means responsive to the creation of the new calling condition on said line for causing said line relay to remain operated to said second position subsequent to the restoration of said cut-off relay, and means controlled when said line relay is operated to said second position and said cut-off relay is restored for marking said line as busy to said automatic switches. 5 10

20. In a telephone system, a line, a plurality 15
of subscriber substations associated with said line,
a number of automatic switches having access to
said line, a line circuit associated with said line
and including line and cut-off relays, said line
relay having first and second operated positions,
means responsive to the initiation of a call at a
calling one of said substations for creating a
calling condition on said line, said line relay being
operative to said first position in response
to the creation of a calling condition on said line,
mechanical means effective to prevent operation
of said line relay to said second position, means
controlled by the operation of said line relay to
said first position for causing an idle one of said
automatic switches to seize said line, said cut-
off relay being operative in response to the seizure
of said line by said one automatic switch, means
controlled by the operation of said cut-off relay
for actuating said mechanical means, whereby
said line relay is operated to said second position,
impulse responsive means operative to cause
ringing current to be projected by way of said
one automatic switch over said line subsequent
to the termination of the calling condition there-
on and to cause said cut-off relay to remain op-
erated, means responsive to the answering of the
call at a called one of said substations for caus-
ing said one automatic switch to be released and
for creating a new calling condition on said line,
said cut-off relay being restored in response to
the release of said one automatic switch, said
line relay remaining operated to said second po-
sition subsequent to the restoration of said cut-
off relay in response to the creation of the new
calling condition on said line, and means con-
trolled when said line relay is operated to said
second position and said cut-off relay is restored
for marking said line as busy to said automatic
switches. 25 30 35 40 45 50

21. In a telephone system, a line provided with at least one line conductor, a plurality of subscriber substations associated with said line, a number of automatic switches having access to said line, a line circuit associated with said line and including line and cut-off relays, said line relay having first and second operated positions, a first circuit including said line conductor for said line relay, a holding circuit for said line relay, means responsive to the initiation of a call at a calling one of said sub-stations for creating a calling condition on said line, said first circuit being completed in response to the creation of a calling condition on said line, whereby said line relay is operated to said first position, means controlled by the operation of said line relay to said first position for causing an idle one of said automatic switches to seize said line, said cut-off relay being operative in response to the seizure of said line by said one automatic switch, means controlled by the operation of said cut-off relay

for completing said holding circuit and for interrupting said first circuit, whereby said line relay is operated to said second position, impulse responsive means operative to cause ringing current to be projected by way of said one automatic switch over said line subsequent to the termination of the calling condition thereon and to cause said cut-off relay to remain operated, means responsive to the answering of the call at 10 a called one of said substations for causing said one automatic switch to be released and for creating a new calling condition on said line, said cut-off relay being restored in response to the release of said one automatic switch, means controlled by the restoration of said cut-off relay for completing said first circuit and for interrupting said holding circuit, whereby said line relay remains operated to said second position in response to the creation of the new calling condition 20 on said line, and means controlled when said line relay is operated to said second position and said cut-off relay is restored for marking said line as busy to said automatic switches.

22. In a telephone system, a line, a plurality 25 of subscriber substations associated with said line, a number of finder-selector links having access to said line, a line circuit associated with said line and including line and cut-off relays, a distributor associated with said links and operative to cause the finder switch of an idle one of said links to operate and seize a line marked as a calling line, said line relay having first and second operated positions, means responsive to the initiation of a call at a calling one of said substations for creating a calling condition on said line, means responsive to the creation of a calling condition on said line for causing said line relay to be operated to said first position, means controlled by the operation of said line relay to said first position for initiating operation of said distributor and for marking said line as a calling line, means responsive to the seizure of said line by the finder switch of said one link for causing said cut-off relay to be operated, means controlled by the operation of said cut-off relay for causing said line relay to be operated to said second position, means controlled by the operation of said line relay to said second position for arresting the operation of said distributor, impulse responsive means included in the selector switch of said one link and operative to cause ringing current to be projected by way of said one link over said line subsequent to the termination of the calling condition thereon and to cause said cut-off relay to remain operated, means responsive to the answering of the call at a called one of said substations for causing said one link to be released and for creating a new calling condition on said line, means responsive to the release of said one link for causing said cut-off relay to be restored, means responsive to the creation of the new calling condition on said line for causing said line relay to remain operated to said second position subsequent to the restoration of said cut-off relay, and means controlled when said line relay is operated to said second position and said cut-off relay is restored for marking said line as busy to said links.

23. A line circuit adapted for use in a telephone system including a line accessible to a number of finder switches and a number of connector switches, said line circuit comprising, in combination, line and cut-off relays, said line relay having a restored position and first and second operated positions, means responsive to the

creation of a calling condition on said line for causing said line relay to be operated from its restored position to its first operated position, means controlled by the operation of said line relay to its first operated position for marking said line as busy to said connector switches, means responsive to the seizure of said line by said automatic switch for causing said cut-off relay to be operated, means controlled by the operation of said cut-off relay for causing said line relay to be operated to its second operated position, and circuits for controlling said finder switches and said connector switches governed in accordance with the positions of said line and cut-off relays.

24. A line circuit adapted for use in a telephone system including a line accessible to a number of finder switches and a number of connector switches, said line circuit comprising, in combination, line and cut-off relays, said line relay having a restored position and first and second operated positions, said line relay being operative from its restored position to its first operated position in response to the creation of a calling condition on said line, mechanical means effective to prevent operation of said line relay to its second operated position, means controlled by the operation of said line relay to its first operated position for marking said line as busy to said connector switches, said cut-off relay being operative in response to the seizure of said line by one of said finder switches, means controlled by the operation of said cut-off relay for actuating said mechanical means, whereby said line relay is operated to its second operated position, and circuits for controlling said finder switches and said connector switches governed in accordance with the positions of said line and cut-off relays.

25. In a telephone system, a line, a number of finder switches and a number of connector switches having access to said line, a line circuit associated with said line and including line and cut-off relays, said line relay having a restored position and first and second operated positions, means responsive to the creation of a calling condition on said line for causing said line relay to be operated from its restored position to its first operated position, means controlled by the operation of said line relay to its first operated position for marking said line as busy to said connector switches and for causing an idle one of said finder switches to seize said line, means responsive to the seizure of said line by said one finder switch for causing said cut-off relay to be operated, means controlled by the operation of said cut-off relay for causing said line relay to be operated to its second operated position, and circuits for controlling said finder switches and said connector switches governed in accordance with the positions of said line and cut-off relays.

26. A line circuit adapted for use in a telephone system including a line accessible to a number of finder and connector switches, said line circuit comprising, in combination, line and cut-off relays, said line relay having first and second operated positions, means responsive to the creation of a calling condition on said line for causing said line relay to be operated to said first position, means controlled by the operation of said line relay to said first position for marking said line as busy to said connector switches, means responsive to the seizure of said line by one of said finder switches for causing said cut-off relay to be operated, means controlled by the

operation of said cut-off relay for causing said line relay to be operated to said second position, means for releasing said one finder switch, means responsive to the release of said one finder switch 5 for causing said cut-off relay to be restored, means for causing said line relay to remain operated to said second position subsequent to the restoration of said cut-off relay in the event a calling condition remains on said line, 10 and additional means controlled when said line relay is operated to said second position and said cut-off relay is restored for marking said line as busy to said connector switches.

27. In a telephone system, a line, a number of 15 finder and connector switches having access to said line, a line circuit associated with said line and including line and cut-off relays, said line relay having first and second operated positions, means responsive to the creation of a calling condition on said line for causing said line relay to be operated to said first position, means controlled by the operation of said line relay to said first position for marking said line as busy to said connector switches and for causing an idle 20 one of said finder switches to seize said line, means responsive to the seizure of said line by said one finder switch for causing said cut-off relay to be operated, means controlled by the operation of said cut-off relay for causing said 25 line relay to be operated to said second position, means for releasing said one finder switch, means responsive to the release of said one finder switch for causing said cut-off relay to be restored, means for causing said line relay to be 30 main operated to said second position subsequent to the restoration of said cut-off relay in the event a calling condition remains on said line, and additional means controlled when said line relay is operated to said second position and 35 said cut-off relay is restored for marking said line as busy to said connector switches.

28. In a telephone system, a line, a plurality of subscriber substations associated with said line, a number of finder and connector switches 40 having access to said line, a line circuit associated with said line and including line and cut-off relays, said line relay having first and second operated positions, means responsive to the initiation of a call at a calling one of said substations for creating a calling condition on said line, means responsive to the creation of a calling condition on said line for causing said line relay to be operated to said first position, means controlled by the operation of said line relay to said 45 first position for marking said line as busy to said connector switches and for causing an idle one of said finder switches to seize said line, means responsive to the seizure of said line by said one finder switch for causing said cut-off relay to be operated, means controlled by the operation of said cut-off relay for causing said line relay to be operated to said second position, impulse responsive means operative to cause ringing current to be projected by way of said one finder 50 switch over said line subsequent to the termination of the calling condition thereon and to cause said cut-off relay to remain operated, means responsive to the answering of the call at a called one of said substations for causing said one finder switch to be released and for creating a new calling condition on said line for causing said line relay to be operated to said first position, means controlled by the operation of said line relay to said first position for marking said line as busy to said connector switches.

relay to remain operated to said second position subsequent to the restoration of said cut-off relay, and additional means controlled when said line relay is operated to said second position and said cut-off relay is restored for marking said 5 line as busy to said connector switches.

29. In a telephone system, a line, a plurality of subscriber substations associated with said line, a number of finder and connector switches having access to said line, a line circuit associated with said line and including line and cut-off relays, said line relay having first and second operated positions, means responsive to the initiation of a call at a calling one of said substations for creating a calling condition on said 10 line, said line relay being operative to said first position in response to the creation of a calling condition on said line, latching means effective to prevent operation of said line relay to said second position, means controlled by the operation of said line relay to said first position for marking said line as busy to said connector switches and for causing an idle one of said finder switches to seize said line, said cut-off relay being operative in response to the seizure 15 of said line by said one finder switch, means controlled by the operation of said cut-off relay for releasing said latching means, whereby said line relay is operated to said second position, impulse responsive means operative to cause ringing current to be projected by way of said one finder switch over said line subsequent to the termination of the calling condition thereon and to cause said cut-off relay to remain operated, means responsive to the answering of the call 20 at a called one of said substations for causing said one finder switch to be released and for creating a new calling condition on said line, said cut-off relay being restored in response to the release of said one finder switch, said line 25 relay remaining operated to said second position subsequent to the restoration of said cut-off relay in response to the creation of the new calling condition on said line, and additional means controlled when said line relay is operated to said second position and said cut-off relay is restored for marking said line as busy to said connector switches.

30. In a telephone system, a line, a plurality of subscriber substations associated with said line, a number of finder-connector links having access to said line, a line circuit associated with said line and including line and cut-off relays, a distributor associated with said links and operative to cause the finder switch of an idle one 50 of said links to operate and seize a line marked as a calling line said line relay having first and second operated positions, means responsive to the initiation of a call at a calling one of said substations for creating a calling condition on said line, means responsive to the creation of a calling condition on said line for causing said line relay to be operated to said first position, means controlled by the operation of said line relay to said first position for marking said line as busy to the connector switches of said links 55 for initiating operation of said distributor and for marking said line as a calling line, means responsive to the seizure of said line by the finder switch of an idle one of said links for causing said cut-off relay to be operated, means controlled by the operation of said cut-off relay for causing said line relay to be operated to said second position, means controlled by the operation of said line relay to said second position 60 for marking said line as busy to the connector switches of said links for initiating operation of said distributor and for marking said line as a calling line, means responsive to the seizure of said line by the finder switch of an idle one of said links for causing said cut-off relay to be operated, means controlled by the operation of said cut-off relay for causing said line relay to be operated to said second position, means controlled by the operation of said line relay to said second position 65 for marking said line as busy to the connector switches of said links for initiating operation of said distributor and for marking said line as a calling line, means responsive to the seizure of said line by the finder switch of an idle one of said links for causing said cut-off relay to be operated, means controlled by the operation of said cut-off relay for causing said line relay to be operated to said second position, means controlled by the operation of said line relay to said second position 70 for marking said line as busy to the connector switches of said links for initiating operation of said distributor and for marking said line as a calling line, means responsive to the seizure of said line by the finder switch of an idle one of said links for causing said cut-off relay to be operated, means controlled by the operation of said cut-off relay for causing said line relay to be operated to said second position, means controlled by the operation of said line relay to said second position 75 for marking said line as busy to the connector switches of said links for initiating operation of said distributor and for marking said line as a calling line.

for arresting the operation of said distributor, impulse responsive means included in the connector switch of said one link and operative to cause ringing current to be projected by way of 5 said one link over said line subsequent to the termination of the calling condition thereon and to cause said cut-off relay to remain operated, means responsive to the answering of the call at a called one of said substations for causing said one link to be released and for creating 10 a new calling condition on said line, means responsive to the release of said one link for causing said cut-off relay to be restored, means responsive to the creation of the new calling condition 15 on said line for causing said line relay to remain operated to said second position subsequent to the restoration of said cut-off relay, and additional means controlled when said line re-

lay is operated to said second position and said cut-off relay is restored for marking said line as busy to the connector switches of said links.

31. A line circuit adapted for use in a telephone system including a line accessible to an 5 automatic switch, said line circuit comprising, in combination, line and cut-off relays, means responsive to the creation of a calling condition on said line for causing said line relay to be energized, means responsive to the seizure of said 10 line by said automatic switch for causing said cut-off relay to be energized, additional means controlled by the operation of said cut-off relay for causing said line relay to be energized, and circuits for controlling said automatic switch 15 governed by said line and cut-off relays.

CLARENCE E. LOMAX.
